UNITED STATES PATENT OFFICE.

JOHN C. WAHL, OF CHICAGO, ILLINOIS, ASSIGNOR, BY DIRECT AND MESNE ASSIGNMENTS, TO WAHL ADDING MACHINE COMPANY, OF CHICAGO, ILLINOIS, A CORPORATION OF ILLINOIS.

CALCULATING-MACHINE.

No. 893,718.

Specification of Letters Patent.

Patented July 21, 1908.

Application filed April 17, 1905. Serial No. 256,141.

To all whom it may concern.:

Be it known that I, JOHN C. WAHL, citizen of the United States, residing at Chicago, in the county of Cook and State of Illinois, have 5 invented a certain new and useful Improvement in Calculating-Machines, of which the following is a full, clear, concise, and exact description, reference being had to the accompanying drawings, forming a part of this 10 specification.

My invention relates to calculating devices and more particularly to compact calculating devices adapted for separable attachment to typewriting machines for automatically performing calculations.

The device of my invention is more particularly adapted for calculations of addition and subtraction and may be directly associated with the number keys of any make of 20 typewriting machine and with the escapement carriage, and upon actuation of the keys the corresponding numbers will be printed upon the sheet and simultaneously registered on the indicator, and at the end of a calculation 25 the desired result will be printed on the sheet and also shown on the indicator.

A totalizer frame with a desired number of totalizer wheels is suitably connected with the escapement carriage upon travel of 30 which the totalizer frame is horizontally moved across the front of the typewriting machine. Driving mechanism for actuating successive totalizer wheels is mounted below the totalizer frame and suitably connected 35 with the number keys, this driving mechanism being relatively stationary. When a calculation is to be performed, such as addition for instance, a proper starting position for the carriage is set in a manner well known, 40 and upon striking of the number and spacing keys the numbers of one sum are placed on the totalizer and simultaneously on the sheet, whereupon the carriage is moved again to its initial position and the next sum 45 accumulated on the totalizer and placed on the sheet in proper order below the first number and so on, and at the end of the calculation the sum total of all the numbers will be indicated on the totalizer. Reversing mech- 50 anism is provided for the device to reverse the rotation thereof upon actuation of the number keys, and the device being set to the reverse or subtracting position the operator strikes off on the keys the sum total indi- 55 cated on the totalizer. This sum total will

appear in proper order at the foot of the column of sums added, but, owing to the reverse movement of the totalizer wheels, these will be returned to the zero position, and when the device is again set for forward rotation it will be in condition for another calculation.

Upon striking of the keys great momentum is given the operative and actuating parts, and heretofore in calculating machines the great trouble has been the tendency for these parts to move farther than desired, the result being that instead of the totalizer wheels rotating the desired distance to indicate the desired number, these wheels will rotate beyond the desired number and the totalizer will not agree with the numbers printed on the sheet. Many mechanisms and arrangements have been proposed for remedying these inefficiencies but have not met with very much success, and one of the main objects of my invention is to provide absolutely reliable locking mechanism, which under all conditions, will prevent over-rotation of the parts and will cause them to be moved precisely as desired. In such devices also much error may result owing to lost motion, and as the interrelated mechanisms in devices like this must necessarily be more or less numerous, any error will be multiplied when it reaches the totalizer indicating wheels and may be sufficient to extend over several numbers. This is particularly true in the totalizer wheel actuating mechanisms themselves. It is well known that in a totalizer certain points may be reached at which all the totalizer wheels will move at the same time upon actuation of one of the wheels, and if there is any lost motion between the adjoining mechanisms the error will be very greatly multiplied. Another feature of my invention, therefore, is the provision of apparatus so constructed and arranged as to reduce lost motion to a minimum.

My invention also comprises several arrangements tending to prevent the occurrence of false actuations of the keys and other apparatus and also includes other features of construction and arrangement, all of which will be best understood by reference to the accompanying drawings, in which

Figure 1 is a side elevation of a typewriting machine showing the calculator attachment associated therewith. Fig. 2 is a front ele-

vation of the typewriting machine with the calculating mechanism attached. Fig. 3 is a detached view of the calculating mechanism and actuating mechanism therefor, parts 5 being shown in section and parts being broken away for clearness. Fig. 4 is a view similar to Fig. 3 showing the apparatus in a different operative position. Fig. 5 is a front view of the parts shown in Figs. 3 and 10 4. Fig. 6 is a detached side view of the main driving member showing its attachment to an actuating shaft. Fig. 7 is a detached view of the totalizer frame showing the manner 15 of arrangement and operation of the totalizer mechanisms, parts being removed for clearness. Figs. 8, 9 and 10 show sectional views of levers for causing movements of different parts to be disengaged. Fig. 11 is a detached view of the adjusting rack for the 20 tabulating mechanism. Fig. 12 shows a suitable attachment between two actuating members.

25 Like reference characters refer to like parts throughout the various figures.

I have shown my device attached to a well-known Remington typewriting machine, although it may be attached with equal facility 30 to other machines. A horizontal supporting bar 1 is secured to hangers 2—2 fastened to the frame 3 of the typewriter by means of screws 4—4 as best shown in Fig. 2. This frame has an upper and a lower raceway or 35 track 5 and 6 respectively adapted to be engaged by upper rollers 7 and lower rollers 8 pivoted from shafts 9 extending from the back of the totalizer supporting frame 10. This frame is thus adapted for longitudinal 40 travel along the track bar 1 and the arm 11 connects with this frame and with a bar 12 secured to the typewriter carriage. This bar 12 extends upwardly and rearwardly along the sides of the typewriter as best 45 shown in Fig. 1, and its rear end is secured to the stationary part 13 of the carriage by means of screws 14. As the typewriter carriage moves across the machine, the frame 10 is carried therewith, and, owing to this manner 50 of attaching the rod 12 to the stationary part of the carriage, the front part of the carriage supporting the type roller may be swung without in any way interfering with the totalizers. The end of the arm 11 is 55 adapted for separable engagement with the lower end of the bar 12 and thus the calculating attachment may be entirely separated from the typewriting machine which may then be used in its ordinary capacity. For 60 this purpose the end of the arm 11 is provided with a rotatable cap 15 having a knurled thumb head 16 and a lateral projection or tongue 17 for engagement in a groove or slot 18 at the forward end of the bar 12.

65 When the calculating device is to be util-

ized the cap is rotated to insert the tongue into the slot, and to disengage the calculating device the cap is rotated to withdraw the tongue from the slot and the carriage will move independently of the calculating mechanism.

The upper and lower edges of the traveling supporting frame 10 are provided with V-shaped guideways or channels 19 and 20, and a totalizer frame 21 has side walls 22 and 23 and provided at their rear, upper and lower edges with V-shaped tongues or projections 24 and 25 for engaging in the channels 19 and 20. This totalizer frame is thus adjustable horizontally along the traveling supporting frame or bar 10, and as the carriage escapes this totalizer frame will be carried across the front of the machine with the traveling supporting bar. To secure the totalizer frame in any adjusted position on the traveling bar a locking lever 26 is pivoted to one of the side walls of the totalizer frame and its end 27 is adapted for engagement in any of the slots 28 cut along the top front edge of the traveling frame 10. These slots 90 are scaled to correspond to the spacing distances of the typewriting machine so that the starting point of the totalizer may agree with that of the typewriter.

As will be more fully described later, a 95 plurality of totalizer gear wheels 121 are pivoted in a horizontal row within the totalizer frame, these gears being suitably connected with the indicating number wheels and other mechanisms. Depending from the bar 1 are 100 arms 30 and 31 terminating respectively in vertical side plates 32 and 33, the arms being also connected by a vertical supporting plate 34. At about the center of this supporting plate 34 is mounted the driving 105 frame 35 consisting of the side plates 36 and 37 which may be secured to the supporting plate 34 by the screws 38. Pivoted in the top forward end of the side plates is a shaft 39 supporting the gear wheel 40. To the 110 rear of the shaft 39 is pivoted another shaft 41 upon which is pivoted the gear wheel 42 which at all times is in mesh with the gear wheel 40. Pivoted in the front end of the side plates 32 and 33 is an actuating shaft 43 115 to which is attached a driving member 44 in the shape of a segmental gear adapted to mesh either directly with the gear wheel 40 or with the gear wheel 42. Suitable switching mechanism, which will be more clearly 120 illustrated hereafter, is provided and is associated with the main driving member and the gear wheel 42. Upon actuation in one direction of this switching mechanism the main driving member will mesh with the 125 gear wheel 40 only, and as this gear 40 is adapted to mesh with the totalizer gear wheels as the totalizer frame travels across the machine, these totalizer gear wheels will be given forward rotation, that is, the num- 130

bers on the number wheels will rotate from smaller to larger numbers. Upon actuation of this switching mechanism in another direction the main driving gear will be in mesh with the gear wheel 42 only, and with this relation the gear 40 which remains in mesh with the gear wheel 42 will cause reverse rotation of the totalizer gear and number wheels. In other words, when the main driving gear meshes directly with the forward gear 40 the totalizer mechanism will add and when the main driving gear meshes with the reverse gear 42 the totalizer mechanism will subtract.

To the rear of the actuating shaft 43 is a pivot shaft 45 to which are pivoted a plurality of actuating cam frames 46 in suitable position over the number keys of the typewriting machine, one of said cam frames being connected with each number key by an adjustable turn buckle 47, and thus upon actuation of any number key the corresponding cam frame will be rotated about the pivot shaft 45. An arm 48 extends forwardly from each cam frame and terminates in a cam surface 49. To the actuating shaft 43 are firmly secured a plurality of actuating arms 50 suitably positioned with respect to the actuating cam frames, and each arm terminates in a cam post or roller 51 for engagement with the cam surface of the corresponding cam frame. Upon depression of a number key the corresponding cam frame will be rotated and its cam surface moved in engagement with the corresponding actuating arm to cause rotation of the actuating shaft and of the main driving gear connected thereto. The rotation of the totalizer number wheels must correspond to the key depressed, that is, if key 1 is depressed the corresponding totalizer number wheel should be rotated 1 division, and likewise if the key 9 is depressed the corresponding totalizer number wheel should be rotated 9 divisions and so on. The rotation, however, of the number wheels will depend upon the arc of rotation of the main driving member, and the actuating arms are consequently regularly angularly displaced on the actuating shaft as best shown in Figs. 3 and 4. The actuating arm corresponding to key 1 is so arranged that upon actuation of the key this arm will be rotated a distance sufficient to cause proper rotation of the main driving member to cause the corresponding number wheel to be rotated only one number. The actuating arm corresponding to key 2 will be slightly angularly displaced from actuating arm 1 to rotate the actuating shaft through a greater arc upon actuation of key 2, and the number wheel engaged will be rotated two numbers. All the other actuating arms are proportionately displaced to cause the proper angular rotation of the main driving gear corresponding at all times to the number key depressed. To cause more regular

actuation of the actuating arms and to prevent over-actuation thereof due to the sudden impact with the cam surface upon striking of the number keys, the cam arm is in the form of a gooseneck, (see Figs. 3 and 4) that is, the retaining arm 52 extends forwardly over the cam surface and thus confines the travel of the cam post or roller in engagement at all times with the cam surface.

Pivoted between the side plates 32 and 33 and disposed between the actuating shaft and the pivot shaft 45 is a locking shaft 53 from which extends a plurality of teeth 54, one for each cam frame. Each cam frame has a wing-like projection 55 provided at its upper edge with teeth 56 arranged in the arc of a circle having its center at the pivot shaft axis. Between the cam arm 48 and the teeth 56 is a depression 57, and when the cooperating tooth 54 is in position, either above this depression or beyond the other end of the tooth, the cam frame may be rotated. However, upon part rotation of a cam frame in one direction the corresponding tooth will engage the teeth and will prevent return of the cam frame from this intermediate position, it being necessary before the frame can be returned that it be rotated the entire distance, that is, to bring the teeth either to the depression 57 or beyond the other end of the teeth. In this manner further operation of the calculating mechanism is prevented until the keys have been properly struck to carry the cam frames beyond the locking point thereof by the locking teeth. A spring 58 connected with the lock shaft 53 and with a stationary part of the framework tends to prevent rotation of the lock shaft, and thus serves to mesh the locking teeth in engagement with the teeth on the cam frames.

As best shown in Figs. 5 and 1 the actuating shaft, the locking shaft and the pivot shaft are maintained in alinement by the plate 59 to which is pivoted an adjustable stop plate 60 having at its forward end an eccentric surface 61 which is engaged by one of the actuating arm cam shafts to limit the return rotation of the actuating shaft and mechanisms connected therewith upon release of the number keys, the return of the shaft 43 to be accomplished by the spring 62 connected therewith and with the stationary frame at some point. This stop is shown as engaging the cam post 63 extending from the actuating arm corresponding to key number 6, the post being elongated sufficiently for this purpose. The position in which the actuating shaft is stopped can be adjusted by virtue of this eccentric cam surface.

Extending from the side plate 36 of the driving frame is a pivot post 64 to the end of which is pivoted a pawl lever 65 having the pawl point 66 for engaging between the teeth of the reverse gear 42. A weighted arm 67 extends from the pawl arm, and a spring 68

connected with the supporting plate 34 and with the extension 69 from the pawl arm tends to maintain the pawl point in engagement with the reverse gear teeth, the weighted arm upon release of the pawl frame providing momentum for this lever to insure its proper engagement with the reverse gear teeth, this being best shown in Figs. 3 and 4. Above the pivot post 64 is pivoted the rock shaft 70 between the side walls 36 and 37, and secured thereto is a retaining arm 71 extending forwardly and sidewardly into engagement with the projection 72 from the pawl arm. Also secured to the rock shaft 10 and extending downwardly therefrom is a lever 73 terminating at its end in a pivot stud 74. Secured to the lock shaft 53 in position below the lever 73 is an upwardly extending arm 75 terminating at its free end in the pivot 20 stud 76. A link member 77 has a slot 78 at its upper end and a slot 79 at its lower end engaged respectively by the pivot studs 74 and 76, a tension spring 80 being connected between the stud 74 and the extension 81 25 from the upper end of the link 77. With this arrangement and immediately upon rotation of a cam frame upon depression of a key the corresponding locking tooth on the lock shaft will be actuated to cause a slight 30 rotation of the lock shaft and this rotary motion will be transmitted through the arm 75, link 77, lever 73, rock shaft 70 and detaining lever 71, whereupon the detaining lever will be moved downwardly to rotate the pawl 35 frame and thereby to disengage the pawl point from the reverse gear, and after this is done the cam surface of the actuated cam frame will engage the corresponding actuating arm to produce proper rotation of the 40 main driving member. Although the slotted link 77 affords direct connection between the arm 75 and the lever 73 this connection is at all times more or less yielding on account of the spring 80, and the vibrations of the lock- 45 ing teeth as they engage the teeth on the cam frames are cushioned. The locking tooth actuated will engage the teeth on the cam frame until the cam surface has given the desired rotation to the actuating arm, and the tooth thereafter will be released from the cam frame, whereupon the locking shaft by means of the spring 58, and also partly by means of the springs 68 and 80, will be returned to its normal position, 55 and the detaining lever and its actuating mechanism will also be returned to the normal position to release the pawl frame, whereby the pawl point may again engage the reverse gear to lock the totalizer mechanism against actuation. Thus provision is made for absolutely locking the totalizer mechanism against actuation except upon active engagement of the cam surfaces with the actuating arms, and errors resulting from

rotating over of the totalizer wheels is entirely eliminated.

Mechanism is also provided for allowing the driving gear to mesh with the forward or reverse gears only when the actuating shaft is rotated. For this purpose the main driving wheel or segment is pivoted to the actuating shaft by the pin 81', the pin passing through the shaft and through the hub 82' to which the driving gear is secured. The bore of the hub is of greater diameter than the actuating shaft, but the shaft is enlarged with 70 in the bore and provided with a circular circumference to form a ball 83', thus forming a sort of ball and socket joint with the hub to allow the main driving member to be swung 75 laterally. A sliding shaft 82 adapted to slide through openings in the side plates 36 and 37 is provided and has a circumferential groove 83 engaging the circular slot 84 in the driving member. Another sliding shaft 85 80 is pivoted in the side walls just below the sliding shaft 82 and to this sliding shaft a bell crank lever 86 is pivoted at its elbow by the pin 87. The upper end of this bell crank 85 lever has a slot 88 engaging the stud 89 extending from the sliding shaft 82, and the other end of this bell crank lever is pivoted to one end of the link 90 which at its other end has a slot 91 engaging the stud 92 extending from the arm 93 secured to and extending forwardly from the lock shaft. The 90 position of this mechanism with respect to the pawl frame moving mechanism is such that both are actuated simultaneously upon depression of a key, this causing primarily a 95 rotation of the lock shaft to cause removal of the pawl frame from the reverse gear and also to cause rotation of the bell crank lever and a sliding of the shaft 82 to carry the main 100 driving gear into connection with either the 105 forward or reverse gear.

As best shown in Fig. 5, the spring 86' serves to hold the bell crank lever in position to maintain the shaft 82 toward the right, whereby the main driving gear is out of mesh 110 with either of the auxiliary driving gears. Upon rotation, however, of the locking shaft, motion is transmitted from the arm 93 to the link 90 through the bell crank lever which is rotated about its pivot to carry the shaft 82 115 toward the left and the main driving gear into mesh with one of the auxiliary gears. The cam surface on the cam arms, however, is active in causing rotation of the main driving wheel only during the time that the corresponding locking tooth is in engagement with the teeth on the cam frame, whereafter the tooth will be released from the cam frame and the locking shaft returned to its normal position by the springs, whereupon the main 120 driving wheel is returned by the spring 86' to its normal position out of meshing engagement. Upon return of a number key

the corresponding cam frame will be rotated rearwardly to bring the teeth thereon beyond the corresponding locking tooth. This backward rotation of the cam frame, however, will 5 produce a slight forward rotation of the locking shaft and of the arms 75 and 93, but as the pivot studs at the end of these arms are disposed within slots at the end of the engaged links, these links and the pawl releasing mechanism and the sliding shaft operating mechanism will not be affected and will 10 remain stationary.

I shall now describe the mechanism for moving either the forward or the reverse auxiliary gear into mesh with the main driving gear.

Pivoted at its lower end to the supporting plate 34 is a lever 94. A link 95 is pivoted to the lever at an intermediate point, and at 20 its other end is pivoted to the actuating plate 96 (see Fig. 5). The lower end of this plate is bifurcated and engages the grooved collar 97 secured to the actuating shaft. The upper end of this actuating plate is secured 25 to the reverse gear shaft which is slidable through the end plates 36 and 37. Near its lower end this actuating plate engages with the sliding shaft 85 to which is pivoted the bell crank lever. The plate is not directly 30 connected to this sliding shaft, but has a latitude of motion along the reduced end 98 of this sliding shaft, and I preferably provide for adjusting this degree of relative motion between the plate and sliding shaft by the 35 use of a screw 99 engaging in the end of this sliding shaft, and the relative motion of the plate with respect to the sliding shaft is determined by the distance between the end of the shaft and the head of the screw. A 40 guiding stud 100 extends from the side plate 36 and forms a guideway for the plate. A detent plate 101 may be secured to the side plate 33 and as shown in Fig. 2 is provided with the notches 102 and 103, a spring 104 45 tending to retain the lever in whichever notch it is placed. When this lever engages in the left notch 102 the reverse gear 42 is moved to the left so that the main driving gear can engage only the forward gear, this forward 50 gear, however, remaining in mesh with the reverse gear. When the lever is placed in the right notch 103 the actuating frame will move to the right the shaft with the reverse gear and the actuating shaft with the main 55 driving wheel to bring the main driving wheel and reverse gear in proper position so that they may mesh upon actuation of the number keys, the movement of the actuating shaft to the right being sufficient to prevent 60 meshing of the main driving gear with the forward gear, and as before stated, with this condition the totalizer gears will be rotated in reverse direction. In other words, when 65 the lever 94 is in the left notch the totalizer mechanism will carry on addition, and when

this lever is in the right notch the totalizer mechanism will carry on subtraction.

A second lever 105 as best shown in Fig. 9 is pivoted to the supporting plate 34 and has a tongue 106 adapted for engagement with 70 the arm 107 secured to the lock shaft, a spring 108 tending to prevent such engagement. The position of the arm 107 is such that when the locking shaft is rotated upon depression of a key it will become disposed 75 below the tongue 106. If for any reason the operator fails to strike the number key sufficiently or should strike two or more keys simultaneously and the teeth on the cam frame are not carried beyond the corresponding 80 locking tooth, an actuation of the lever 105 will cause engagement of the tongue 106 with the arm 107 to rotate the locking shaft to carry the locking tooth thereon from engagement with the teeth on the cam frame of 85 the key which has not been sufficiently moved. Upon thus releasing the locking tooth the cam frame and the key may return to the normal position. The actuating shaft and the main driving gear will also return to 90 their normal positions and the actuated totalizer wheel will also return to its normal position. The key may then be properly struck and the totalizer wheel will properly indicate. A third lever 109 in the shape of a 95 bell crank is pivoted at its elbow to the side plate 33, as best shown in Fig. 10. The forward end thereof terminates in a shoe 110 for engaging the arm 111 extending from the locking shaft, a spring 112 tending normally 100 to prevent such engagement. Upon release of a struck key the teeth upon the corresponding cam frame should be returned beyond the corresponding locking tooth. Unless this is done the tooth will engage these teeth 105 and prevent subsequent depression of the key, but upon actuation of this lever 109 the shoe 110 will engage the arm 111 and will rotate the locking shaft to carry the tooth out of engagement with the cam frame teeth to 110 allow the key to be depressed. This lever 109 also performs another very important function. The rotation of the locking shaft by engagement of the locking teeth thereon with the cam frames is depended upon to carry the 115 main driving wheel into mesh with the auxiliary driving gears, but upon actuation of the lever 109, as before stated, the locking teeth are rotated from the path of the cam frames may be rotated to cause actuation only of the actuating arms and shaft, but the main driving gear will not be moved laterally to be carried into meshing engagement with the auxiliary gears and therefore the totalizer 120 mechanism will not be actuated. This is very desirable where the typewriting machine is intended to be used in its ordinary capacity, which often occurs in the midst of calculating work, and where it is not de- 125 130

sirable that the totalizer mechanism should be entirely disengaged upon actuation of the rotating cap 15. Notches 113 and 114 may be provided in the detent plate 101 for receiving the levers 105 and 109. A fourth lever 115 as shown in Fig. 8 may also be provided connecting with the actuating shaft, as shown, and upon actuation of which the shaft is rotated to hold the actuating arms thereon out of the path of the cam frames. Thus when the lever 115 alone is actuated there may be lateral movement of the main driving gear but not rotational movement thereof, and if the lever 109 alone be actuated there may be rotation of the main driving gear shaft but not lateral movement of the driving member, but if both levers be moved, the main driving shaft and member thereon will remain stationary and the number keys of the machine may be struck to cause actuation only of the cam frames. A locking slot 116 may be provided in the detent plate 101 for this fourth lever.

The totalizer mechanism best shown in Figs. 3, 4, 5 and 7 is contained between the side walls 22 and 23 of the frame 21, these walls, as before stated, being provided at their rear edges with the V-shaped extensions 24 and 25 which engage in the channels 19 and 20 of the traveling frame. A horizontal shaft 117 extends between the side walls at the front and near the middle thereof, and rotatably mounted thereon are the number wheels 118 each provided with a gear wheel 119. To the rear of this shaft is another horizontal shaft 120 extending between the side walls and secured thereto. Rotatably mounted on this shaft are a plurality of totalizer gear wheels or receiving wheels 121, 40 each one meshing with the gear of the corresponding number wheel. The lower part of these gears extends slightly beyond the lower edge of the side walls of the frame 21, and as this frame is carried horizontally across the machine and over the forward auxiliary driving gear of the driving mechanism, this gear will successively mesh with the totalizer gears, and upon depression then of a number key the engaged totalizer 50 wheel will be rotated to revolve the corresponding number wheel a corresponding number of divisions. The totalizer gears are shown as provided with thirty teeth and the gears on the number wheels are provided with ten teeth, making the gearing proportion 3 to 1, and for every one-third of a revolution of a totalizer gear the number wheel will turn one revolution. Secured to the left face of each totalizer gear is a second 60 thin gear plate 122 having three teeth 123 displaced 120 degrees, and adjacent to this gear plate is a cam plate 124 having three notches 125 also displaced 120 degrees and disposed directly opposite the teeth 123, the 65 diameter of this cam plate being slightly less

than that of the gear plate. This gear plate and cam plate constitute part of carry-over mechanism which will presently be described. To the rear of the totalizer gear shaft is the third shaft 126 extending between the side plates, and on this shaft is mounted a set of bell crank levers 127 for supporting the other part of the carry-over mechanism, this consisting of a gear pinion 128 having a pinion wheel 129 and a carry-over gear wheel 130, these parts being secured together and mounted on a pivot stud 131 extending from the end of the bell crank levers. The pinion gear has ten teeth adapted to be engaged by the carry-over teeth 123 on the gear plate 122, and for every one-third of a revolution therefore of the totalizer gear there will be one engagement by the gear plate 122 with the gear pinion 128 to cause a one tooth advancement 75 thereof. The star wheel is provided with ten circular concave surfaces 132 having the same radius as the cam plate 124, these surfaces being in intimate engagement with the unbroken cam surface until a tooth 123 80 comes into engagement with the gear pinion 128, and at this instant the notch 125 corresponding with the engaging tooth 123 will become disposed opposite one of the points 133 on the star wheel. During the 85 interval between the teeth 123 one of the circular surfaces of the star wheel will engage the unbroken surface between the corresponding notches 125 of the cam plate and it is impossible for the star wheel to rotate 90 on account of the greater radius at the points 133 but when a notch 125 arrives below one of these points additional space is afforded for this longer radius and the star wheel may turn and no longer blocks the 95 carry-over apparatus. Thus at every ten advancements of one totalizer gear a tooth 123 will engage the gear pinion 128 on the corresponding carrying-over lever, and at the same instant the star wheel may also 100 rotate, whereupon the carry-over gear which engages the teeth of the next adjacent totalizer gear will cause rotation of this adjacent totalizer wheel. Owing to the 105 dimensions of the gears the adjacent gear wheel will be advanced to cause the engaged number wheel to advance one number. In other words, at each rotation of one number wheel from zero to 9 the next actuation thereof will move it to indicate zero, and at 110 the same instant the carry-over mechanism just described will be actuated to move the next adjacent totalizer number wheel from zero to 1. To afford more compact arrangement of the totalizer mechanisms the bell 115 crank, carry-over and locking mechanism supporting levers are not all mounted on the shaft 126 but part thereof is mounted on the shaft 134 above the shaft 126, these levers being also provided with the same mechan- 120

ism as the other levers just described, this mechanism, however, engaging the totalizer wheels in front of the mechanisms on the other levers in order to allow compactness.

5 As best shown in Figs. 3, 4, and 7 the teeth on the gear wheels and on the gear plates are so formed that when in mesh there will be a minimum of lost motion and so that the gears will carry just the required distance.

10 The downwardly extending end 135 of each of these bell crank levers is connected through a spring 136 with the spring supporting rod 137 which may also be secured to the side plates, and the tendency of these 15 springs is to hold the carry-over gearing mechanism and locking star wheels in engagement with the totalizer gear and cam wheels. The pressure between these parts occasioned by the springs, however, may be controlled by adjustable abutment screws 20 138 extending through the bar 139 secured between the totalizer frame side walls, the upper end of each of these bell crank levers being provided with an abutment projection 25 140 for engaging one of these adjusting abutment screws.

The ends of the downward extensions 135 of these levers are arranged in a straight horizontal row and pass behind a horizontal 30 detaining bar 141 secured to the driving mechanism frame. Each totalizer gear is in mesh with the carry-over gear wheel of the carry-over mechanism associated with the preceding gear wheel. As this carry-over 35 gear is secured to the corresponding star wheel, which is locked against the cam plate of this preceding gear wheel, there can be no rotation of this carry-over gear unless the star wheel is removed from such locking engagement, but to remove the star wheel the corresponding bell crank lever must be rotated, this, however, being prevented by engagement of the foot of the bell crank lever with the horizontal detaining bar on 40 the driving mechanism frame. If this carry-over gear is thus locked against rotation the engaged totalizer gear will also be locked. The lower edge of the detaining bar just preceding the forward auxiliary 45 driving gear is cut away a distance and when the foot of any bell crank lever arrives under this part the bell crank lever may be rotated to carry its star wheel from locking engagement. Thus when the desired 50 totalizer gear is in mesh with the forward driving gear, the foot of the preceding bell crank lever will be at the cut-away part of the detaining bar, and upon depression then of a number key the engaged totalizer 55 wheel may rotate. It is, however, very important that the carry-over gear on this preceding lever should be entirely clear of meshing engagement with the actuated gear wheel, otherwise the entire carry-over 60 mechanism associated with this carry-over

gear would become deranged. To prevent this a releasing arm 142 is secured to the rocker shaft 70 of the driving mechanism, it being before stated that this rock shaft is rotated immediately upon depression of 70 a number key. This releasing arm extends upwardly from this rocker shaft, the end thereof being directly opposite the cut-away portion of the detaining bar and to the right of the plane of the forward driving 75 gear. As a key is now struck to cause rotation of the totalizer gear in mesh with the forward driving gear, this releasing lever will be rotated upwardly upon rotation of the rock shaft and will engage below the 80 foot of the preceding bell crank lever in the totalizer mechanism, the result being that the upper part of this lever will be moved to carry the carry-over gear entirely clear from meshing engagement with the gear 85 wheel to be rotated, and when this gear wheel is finally rotated upon further depression of the key, there will be no resultant motion whatever of the carry-over mechanism. To prevent derangement, however, of 90 the carry-over and locking parts when thus carried out of engagement by virtue of the releasing arm, a tooth or detent 143 is provided for engaging between the teeth of the carry-over gear as it is raised out of engagement with the gear wheel to be actuated, and this tooth may conveniently form part of the bell crank lever corresponding to the gear wheel to be actuated, and thus a tooth extending from one of the levers will prevent 100 displacement of the carry-over and locking mechanism carried by the preceding lever. The detaining bar, the releasing arm, the star wheel mechanism and these detent teeth all coöperate to lock the various parts 105 against any movements other than those which must necessarily result to produce the proper and accurate rotation of the totalizer number wheels. There is, therefore, an absolute reliability of operation and no 110 danger of miscarriage or overcarriage of the mechanisms.

As there is no mechanism provided for carrying over to the first totalizer gear other means must be provided for normally locking this gear in position, and a smaller detent lever 144 is pivoted to the shaft 134, the end 145 of the lower arm thereof being disposed in the same horizontal row with the lower ends of the carry-over levers to be also engaged by the releasing lever. The upper arm of this small bell crank lever normally engages the teeth of this first totalizer gear by virtue of a spring 146. The lower end 120 of this lever is bent a distance toward the right to be disposed opposite the cut-away portion of the retaining bar when this first totalizer gear is in mesh with the forward driving gear, and thus when the key is actuated the releasing arm will engage this end 125 130

145 and will release the other end of the lever from the first totalizer gear, whereupon this gear may be rotated.

The number wheels and the totalizer gears 5 are placed in groups, usually three in a group, *e. g.*—: units, thousands and millions, and so on, there being a space between each group of totalizer gears equal to twice the space of the typewriter spacing distance, and 10 thus when the numbers are printed on the sheet there will be a greater space between these groups, it being then unnecessary to print periods or commas between the groups. Thus the operator when striking off a sum on 15 the keys starts, say in the thousands column, and strikes the numbers in the thousands division whereupon she must strike the spacing key before proceeding to strike off the numbers in the hundreds group and so on. 20 If she should neglect to strike the spacing key between the groups confusion will result, and I therefore provide preventative means in the shape of a plate or bar 147 secured to the side plates of the totalizer frame and having 25 depending teeth which are disposed in register with the spaces between the groups and also adapted to pass between teeth of the forward driving gear of the driving mechanism. Thus when a group spacing division 30 is opposite the forward driving wheel the corresponding tooth will engage the teeth of this driving wheel and prevent its rotation should a number key by mistake be struck, and of course, the totalizing device will be inactive 35 until the spacing key is struck to move the tooth from engagement with the driving wheel.

To cause the teeth of the totalizer gears to readily mesh with the forward driving gear 40 as the totalizer frame is reciprocated, the teeth of the forward driving gear are extended downwardly a distance along the sides of the gear and are beveled, serving thus to guide the totalizer gear teeth into a proper 45 meshing engagement. Also to assist in properly aligning the totalizer gear teeth before they reach the forward driving gear, a guiding edge 148 is secured to the right wall of the driving mechanism frame. A cover 50 149 may also be provided for the totalizer frame having a row of openings 150 through which the characters on the number wheels are visible.

As before stated, the totalizer frame is adjustable along the traveling frame 10, the locking lever 26 and the slots 28 serving for this purpose and the starting position of the totalizer may be adjusted to correspond with that of the typewriting machine. To 55 render it unnecessary for the operator to strike off the spacing on the spacing bar of the typewriter to bring the desired totalizer gear into engagement with the driving gear, tabulating mechanism may be used for this 60 purpose and Figs. 1 and 11 show the well

known form of tabulating mechanism employed in conjunction with typewriters. The tabulating keys 151 are disposed in a horizontal row in the front of the machine and connect by rods 152 with levers 153 pivoted at 154 and terminating in their upper end in the escapement fingers 155. Mounted on the traveling carriage of the typewriter is a bar 156 provided with teeth 157 whose pitch is equal to the pitch of the escapement teeth of the typewriter. The escapement fingers 155 are grouped in the rear of this actuating bar and are spaced to correspond with the teeth 157. Abutments 158 are adapted for adjustable insertion in the 70 teeth of the rack 156 and are spaced thereon to correspond with the spacing between the totalizer gears and the starting point of the typewriting machine. By the proper spacing of these abutments it is necessary 75 only for the operator to depress the proper tabulator key and the escapement carriage will travel directly to bring the corresponding totalizer gear into mesh with the driving gear.

The operation of the device is now apparent. For illustration, suppose it is desired to add a column of sums, then, after the totalizer frame is properly adjusted so that the printed numbers will appear at the proper 80 position on the sheet, and the totalizer number wheels all indicate zero, the proper tabulating key for the first sum is struck, whereafter the number keys of the machine are 85 successively struck to place the remaining 90 numbers of the sum on the totalizers. The escapement carriage is then returned to its initial position, the printing roller being advanced the required distance at the same time. The proper tabulating key is struck 95 for the second sum and the proper number 100 keys struck, this second sum appearing on the sheet under the first sum and in proper alinement therewith, this second sum, however, being added to the first on the totalizer. 105 In the same manner the remaining sums are 110 accumulated on the totalizer and printed in alinement on the sheet. The totalizer at the end of the calculation will indicate the total 115 sum of all the numbers and this sum is then 120 placed below the column of sums on the sheet, the proper mechanism being first, however, actuated to reverse the rotation of the driving mechanism and the result will be 125 that the totalizer number wheels will be returned to zero and the accumulated sum total of the added numbers will be placed on the sheet below the added numbers. The different mechanisms and their operation for producing these results have been sufficiently 130 described before and it will not be necessary to repeat them here.

The device is shown as employing only one totalizer frame, but it is evident that more may be mounted on the traveling frame 130

and thus several columns of sums added at practically the same time.

I thus produce a very useful and efficient device for producing calculations of addition and subtraction which may be removably connected with any typewriting machine without in any way interfering with the ordinary operation of the machine. All the various mechanisms are mounted so that there will be absolute certainty of operation there-
of without any lost motion or with the least amount of motion short of or in excess of that intended. The construction and arrangement of these parts are also very simple, compact and neat in appearance. No additional keys are necessary for the typewriting machine, the calculating being all accomplished by use of the number keys which appear on the typewriter. Although several levers are provided for the mechanism itself they are very seldom used, the one most used being the lever provided for adjusting the mechanism for either addition or subtraction, the other levers being used only for re-
setting or releasing parts when mistakes have been made. The device may be used as an independent machine for adding or subtracting and it need not necessarily be used in connection with a typewriting machine.

Attention is hereby directed to my co-pending application filed Oct. 23, 1905, Serial No. 283,887, wherein I claim some of the devices and combinations of devices herein shown.

Many changes also might be made in the exact construction, arrangement and operation of the parts without departing from the spirit and scope of my invention, and I do not therefore, wish to be limited to the exact disclosure as shown, but

I claim as new and desire to secure by Letters Patent:

1. In a calculating machine, the combination with mechanism for indicating calculations, of actuating gear wheels for said mechanism, a driving gear wheel for engaging said mechanism gear wheels, a main driving member normally out of mesh with said driving gear, keys for said machine, and means upon first actuation of a key for causing said main driving member to be moved laterally to another plane into mesh with said driving gear and upon further actuation of said key to cause rotation of said driving gear and of the mechanism gears.

2. In a calculating machine, the combination with calculating mechanism having actuation gears, of a driving gear for engaging said calculating gears, a main driving member normally out of mesh with said driving gear, keys for said machine, means upon depression of one of said keys for causing said main driving member to be first moved laterally to another plane into mesh with the driving gear and then to be rotated to cause ac-

tuation of the driving gear and of the calculating gears, and means for subsequently causing said main driving member to be removed from meshing engagement with said driving gear.

3. In a calculating machine, the combination with calculating mechanism, of a main driving member for causing actuation of said calculating mechanism, said driving member being normally out of engagement with said calculating mechanism, keys for said machine, and means upon depression of a key for causing said driving member to be first moved laterally to another plane into engagement with said calculating mechanism and then to be rotated to cause actuation of said calculating mechanism.

4. In a calculating machine, the combination with calculating mechanism, of a main driving member for causing actuation of said calculating mechanism, said driving member being normally out of engagement with said calculating mechanism, keys for said machine, means upon depression of a key for causing said driving member to be first moved to another plane into engagement with said calculating mechanism and then to be rotated to cause actuation of said calculating mechanism, and means upon release of a depressed key for causing said driving member to move to its normal plane to become disengaged from the calculating mechanism.

5. In a calculating machine, the combination with calculating mechanism, of a main driving member adapted for causing actuation thereof, said driving member being normally out of engagement with said mechanism, keys for said machine, means upon actuation of a key for causing first lateral movement of said main driving member to bring said member into engagement with the calculating mechanism, means upon further actuation of said key for causing rotation of said driving member to cause actuation of the calculating mechanism, and means after rotation of said member for moving said member laterally out of engagement with said calculating mechanism.

6. In a calculating machine, the combination with indicating mechanism, of a main driving member for causing actuation of said indicating mechanism, said member being normally out of driving engagement with said mechanism, means for causing lateral motion of said member to bring said member into engagement with said mechanism, means thereafter for rotating said rotatable member to cause actuation of indicating mechanism parts, and means after such actuation of indicating mechanism for returning said member to its former position out of driving relation with said mechanism.

7. In a calculating machine, the combination with indicating mechanism, of a main

driving member therefor, actuating keys for said machine, a shaft to which said driving member is pivoted and adapted for lateral movement, means upon actuation of a key 5 for causing first a lateral movement of said driving member to bring said member into driving relation with the indicating mechanism, means upon further actuation of said key to cause rotation of said shaft with said 10 member to produce actuation of the indicating mechanism, and means after such rotation for again removing said member from driving relation with the mechanism.

8. In a calculating machine, the combination 15 with indicating mechanism, of actuating keys, a shaft, mechanism intervening between said shaft and said keys, a main driving member pivoted to said shaft and adapted to swing laterally thereon, means for normally retaining said member out of driving 20 relation with the indicating mechanism, and means upon depression of a key for causing said driving member to be first swung laterally into driving relation with the indicating mechanism, continued actuation of said key 25 causing rotation of said shaft and said driving member whereby the indicating mechanism is actuated.

9. In a calculating machine, the combination 30 with indicating mechanism, of a driving member adapted for lateral and rotatable movement and normally out of driving relation with the mechanism, keys for the machine associated with said main driving member, actuation of a key causing lateral movement 35 of said member into driving relation with the indicating mechanism, and then rotation of said member to cause actuation of the indicating mechanism.

40 10. In a calculating machine, the combination with indicating mechanism, of a driving member adapted for lateral and rotatable movement and normally out of driving relation with the mechanism, keys for the machine associated with said main driving member, actuation of a key causing lateral movement 45 of said member into driving relation with the indicating mechanism, and then rotation of said member to cause actuation of the indicating mechanism, and means for determining in which direction the indicating mechanism shall be actuated.

11. In a calculating machine, the combination 55 with indicating mechanism having actuating gear wheels, of a laterally movable main driving member, a driving gear for meshing with said indicating mechanism gear wheels, a laterally movable reversing gear wheel, said driving member normally upon 60 actuation being in mesh with the driving gear to cause rotation thereof and of the actuating gear wheels in a forward direction, and means for laterally moving both the main driving member and the reversing gear into 65 mesh with each other whereby upon actua-

tion of the driving member the actuating gear wheels will be moved in a reversed direction.

12. In a calculating machine, the combination 70 with indicating mechanism having actuating gear wheels, of a main driving member, a forward gear for meshing with said indicating mechanism gear wheels, a reverse gear in mesh with the forward gear, said main driving member upon actuation being normally in mesh with the forward gear, and means 75 for causing motion of both the reverse gear and the main driving member into mesh with each other and the main driving member out of mesh with the forward gear.

13. In a calculating machine, the combination 80 with indicating mechanism having actuating gear wheels, of a main driving member having both lateral and rotational movement, a forward driving gear for meshing with the indicating mechanism gear wheels, a reverse 85 gear wheel having meshing engagement with said forward gear, keys for the machine, means upon actuation of a key for causing first the lateral motion of the main driving member into mesh with the forward gear and then rotational movement to cause rotation of the forward gear and indicating mechanism gear wheels, and means for moving the reverse gear and the main driving member laterally 90 whereby the driving member is carried from meshing engagement with the main driving gear and into meshing engagement with the reverse gear.

14. In a calculating machine, the combination 100 with indicating mechanism having actuating gear wheels, of a forward gear for meshing with said gear wheels, a reverse gear meshing with said forward gear, a main driving member, a pivot shaft for said driving member, keys associated with said driving member shaft, said driving member being adapted to swing laterally on said shaft, means normally upon depression of a key for first causing said driving member to swing laterally into mesh with the forward driving gear and then to be rotated to cause rotation of the forward gear and indicating mechanism gear wheels, and means for causing lateral movement of the reverse gear and of the main driving gear shaft whereby subsequent 110 actuation of a key will cause first lateral motion of the main driving member to mesh only with the reverse gear and to be rotated to cause rotation of the reverse gear and reverse rotation of the indicating mechanism 115 gear wheels.

15. In a calculating machine, the combination 120 with indicating mechanism having actuating gear wheels, of a forward driving gear for meshing with the actuating gear wheels, a reverse gear meshing with the forward driving gear, a main driving member, an actuating shaft for said main driving member, keys associated with said shaft, said main driving member having lateral motion relative to 130

5 said shaft, said driving member upon actuation of a key being normally in mesh with the forward driving gear to cause forward actuation of the indicating mechanism, and means 10 for moving the reverse gear and the shaft with the main driving member whereby upon subsequent actuation of a key the main member will be in mesh with the reverse gear whereby to cause reverse actuation of 15 the indicating mechanism.

16. In a calculating machine, the combination with traveling indicating mechanism, of stationary driving mechanism, an actuating shaft for said driving mechanism, a main 15 driving member pivoted to said shaft to rotate therewith and to swing laterally thereon, gearing mechanism for engaging with said main driving member and said indicating mechanism, said main driving member being 20 normally out of engagement with said gearing mechanism, a plurality of actuating arms extending from said actuating shaft, keys for said machine, cam frames secured to said keys, and mechanism associated with 25 said cam frames and said main driving member, actuation of a key primarily causing engagement of the corresponding cam frame with said mechanism to move the driving member into engagement with the gearing 30 mechanism, further actuation of said key causing engagement of the cam frame with the corresponding actuating arm whereby the main driving member is rotated and the indicating mechanism actuated through the 35 gearing mechanism.

17. In a calculating machine, the combination with traveling indicating mechanism, of stationary driving mechanism therefor, gearing mechanism for engagement with the indicating mechanism, a main driving member adapted for engagement with said gearing mechanism, an actuating shaft to which said driving member is pivoted and from which it may swing laterally, actuating arms extending 40 from said actuating shaft, keys for said machine, a pivot shaft, cam frames on said pivot shaft and connected with said keys for engagement with said actuating arms, a locking shaft, teeth extending from said locking 45 shaft for engagement with said cam frames, and mechanism intervening between said lock shaft and the free end of said main driving member, depression of a key causing first actuation of said lock shaft and the intervening mechanism to swing the main driving member into mesh with said gearing mechanism, then causing engagement of the cam frame with the actuating arm to cause 50 rotation of the actuating shaft and the main driving member, whereby said indicating mechanism is actuated.

18. In a calculating machine, the combination with traveling indicating mechanism having rotatable members, of stationary 55 driving mechanism, gearing for said driving

mechanism adapted for engagement with the indicating mechanism, a main driving member, an actuating shaft with which said driving member may rotate and to which it is pivoted to swing laterally, actuating arms 70 extending from said actuating shaft, a pivot shaft, cam frames pivoted to said pivot shaft for engagement with said actuating arms to cause rotation of the actuating shaft and the main driving member, keys for said machine 75 connected with said cam frames, a locking shaft, lever mechanism connected with said shaft and with the free end of the swinging main driving member, means for normally retaining said locking shaft and said lever 80 mechanism in position to hold the main driving member out of meshing engagement with said gearing mechanism, teeth extending from said locking shaft for engagement with said cam frames, actuation of a 85 key causing rotation of the corresponding cam frame, rotation of said cam frame causing first a slight rotation of the locking shaft, whereby the lever mechanism is actuated to swing the free end of the main driving member 90 into meshing engagement with said gearing mechanism and then upon engagement of said cam frame with the corresponding actuating arm causing rotation of the actuating shaft and the main driving member, whereby 95 the gearing mechanism is rotated to actuate the indicating mechanism.

19. In a calculating machine, the combination with traveling indicating mechanism having rotatable actuating parts, of stationary driving mechanism, gearing mechanism for engaging with said indicating mechanism, a main driving member for causing actuation of said gearing mechanism, an actuating shaft to which said main driving member is 100 pivoted and whereon it may swing laterally, actuating arms extending from said actuating shaft, a pivot shaft, cam frames pivoted to said pivot shaft and connected with keys for said machine, teeth on said cam frames, 105 a locking shaft, lever mechanism connected with said locking shaft and the free end of said swinging main driving member, teeth extending from said locking shaft for engagement with the teeth on said cam frames, 110 means for normally retaining said locking shaft and the lever mechanism in position to hold the main driving member out of engagement with the gearing mechanism, and means upon actuation of a key for causing engagement of the corresponding cam frame with a corresponding locking tooth on the locking shaft to cause rotation of said locking shaft and the lever mechanism, whereby the free end of the main driving member is moved to 115 bring said member into mesh with the gearing mechanism, further depression of said key causing said cam frame to be brought into engagement with the corresponding actuating arm, whereby the actuating shaft and 120

the main driving member are rotated to cause rotation of the gearing mechanism and actuation of the indicating mechanism, said teeth on the lock shaft and said teeth on the 5 cam frame coöperating to form pawl and ratchet mechanism which prevents release of a key until depressed a predetermined distance and which prevents subsequent depression of the key unless released through 10 the proper distance.

20. In a calculating machine, the combination with traveling indicating mechanism, of stationary driving mechanism, a frame in which said driving mechanism is disposed, an 15 intermediate driving gear pivoted in said frame and adapted for engagement with the actuating parts of the indicating mechanism, a main driving segmental gear adapted for engagement with said intermediate gear, an 20 actuating shaft, said main driving gear being pivoted to said shaft to rotate therewith and to swing laterally thereon, keys for said machine, a pivot shaft, cam frames pivoted to said pivot shaft and connected with said 25 keys, actuating arms extending from said actuating shaft and associated with said cam frames, a circular slot through the free end of said main driving member, a horizontal sliding shaft having a groove engaging in said 30 slot, a locking shaft, an arm extending from said locking shaft, a bell crank lever connected between said arm and said sliding shaft, and teeth extending from said locking shaft for engagement with the corresponding cam 35 frames, actuation of a key causing rotation of the corresponding cam frame whereby the lock shaft is first rotated to cause actuation of the bell crank lever and the sliding shaft to carry the main driving gear into mesh with the intermediate gear, and whereby the corresponding actuating arm is subsequently engaged to cause rotation of the actuating shaft and the main driving member, whereby the indicating mechanism is actuated, 40 45 said main driving member being returned to its original position out of mesh with said gear upon release of the lock shaft from the cam frame.

21. In a calculating machine, the combination 50 with traveling indicating mechanism, of stationary driving mechanism, an intermediate gear for said driving mechanism for engaging directly with the actuating parts of the indicating mechanism, an actuating shaft for the driving mechanism, a segmental gear pivoted to the actuating shaft to rotate therewith and to swing laterally thereon, a circular slot through the free end of said segmental gear, a sliding shaft having a groove 55 engaging in said slot, a locking shaft, a bell crank pivoted at its elbow to the driving mechanism frame, one end of said crank engaging said sliding shaft and the other end of said crank connected with said locking 60 65 shaft, keys for said machine, cam frames

connected with said keys and pivoted to a pivot shaft, actuating arms extending from said actuating shaft for engagement with said cam frames, and teeth extending from said locking shaft for engagement with said 70 cam frames during part of their rotation, depression of a key causing first a rotation of the locking shaft, whereby the bell crank and sliding shaft are moved to carry the segmental gear into mesh with the intermediate 75 driving gear, the engaged cam frame then causing rotation of the corresponding actuating arm and the actuating shaft, whereby the segmental gear is rotated and the indicating mechanism actuated. 80

22. In a calculating machine, the combination with traveling indicating mechanism, of stationary driving mechanism, gearing mechanism for said driving mechanism for engaging with the actuating parts of the indicating mechanism, a main actuating member for engaging said gearing mechanism to cause rotation thereof, an actuating shaft to which said main member is pivoted, an actuating arm extending from said shaft, a key 90 for said machine, a cam frame connected with said key and pivoted to a pivot shaft, a locking shaft, a tooth extending from said locking shaft for engagement with said locking frame, an arm extending from said locking shaft, a pawl normally engaging said gearing mechanism to prevent rotation thereof, and lever mechanism intervening between said arm and said pawl, depression of said key causing first a slight rotation of the lock 100 shaft whereby said lever mechanism is actuated to release the pawl from said gearing mechanism, further depression of said key causing active engagement of said cam frame with said actuating arm whereby said actuating shaft and said main actuating member are rotated to cause rotation of the released gearing mechanism and the indicating mechanism. 105

23. In a calculating machine, the combination with a traveling indicator, of stationary driving mechanism, gearing mechanism for said driving mechanism for engagement with the actuating parts of the indicator, a main driving member adapted to mesh with said gearing mechanism, an actuating shaft for said main driving member, an actuating arm extending from said shaft, a key for said machine, a cam frame connected with said key and pivoted to a pivot shaft and adapted for engagement with said actuating arm, pawl mechanism normally engaging said gearing mechanism to prevent rotation thereof, a locking shaft, a tooth extending from said locking shaft for engagement with said cam frame, an arm extending from said locking shaft, and lever mechanism connected with said arm and with said pawl mechanism, depression of said key causing actuation of the cam frame to first rotate the locking shaft a 110 115 120 125 130

distance whereby said lever mechanism is actuated to release the pawl mechanism to allow rotation of the gearing mechanism, further actuation of said cam frame causing engagement thereof with the actuating arm, whereby said actuating shaft and main driving member are rotated and the released gearing mechanism rotated to actuate the indicating mechanism, the engagement of said tooth with said cam frame being such that the key will be locked against restoration until depressed its full distance, and locked against subsequent depression until fully restored.

24. In a calculating machine, the combination with a traveling indicator, of stationary driving mechanism, gearing mechanism for said driving mechanism adapted for engagement with the actuating parts of the indicator, a main driving member in the form of a segmental gear for causing rotation of said gearing mechanism, an actuating shaft to which said main driving member is pivoted to rotate therewith and upon which it may swing laterally, an actuating arm extending from said actuating shaft, a key for said machine, a cam frame connected with said key and pivoted to a pivot shaft for engagement with said actuating arm, a locking shaft, a tooth extending from said locking shaft for engagement with said cam frame, bell crank mechanism connected with said locking shaft and with the free end of said main driving member, pawl mechanism normally engaging said gearing mechanism to prevent rotation thereof, lever mechanism connected with said locking shaft and with said pawl mechanism, means for normally retaining said main driving member out of engagement with the gearing mechanism, depression of said key causing said cam frame to be actuated to rotate the locking shaft a distance whereby said pawl mechanism is actuated to release the pawl from the gearing mechanism and whereby said bell crank mechanism is actuated to swing the main driving member into mesh with said gearing mechanism, further depression of the key causing continued actuation of the cam frame which then engages said actuating arm to cause rotation of the main driving member whereby said gearing mechanism is rotated and the indicating mechanism actuated.

25. In a calculating machine, the combination with a traveling indicator, of stationary driving mechanism, an intermediate driving gear for said driving mechanism for directly engaging with the actuating mechanism of the indicator, a main driving member in the form of a segmental gear for engaging said intermediate driving gear, a reverse gear at all times in mesh with said intermediate driving gear, an actuating shaft for said main driving member, said main driving member being pivoted to said shaft to rotate therewith and to swing laterally thereon, a

key for said machine, a cam frame connected with said key and pivoted on a pivot shaft, an actuating arm extending from the actuating shaft for engagement by the cam frame, a locking shaft, a tooth extending from said locking shaft for engagement with said cam frame upon actuation of the key, pawl mechanism normally engaging said reverse gear to prevent rotation of the intermediate driving gear, lever mechanism connected with said locking shaft and with said pawl mechanism, means for withdrawing the pawl from said reverse gear, depression of said key causing first a slight rotation of the locking shaft, whereby the lever mechanism is actuated to release the pawl from the reverse gear and to allow actuation of the intermediate driving gear, continued depression of said key causing the actuating arm to be engaged by the cam frame whereby the main driving member is rotated to cause rotation of the intermediate driving gear and actuation of the indicating mechanism, and means for moving said reverse gear and said main driving member, whereby upon another depression of said key said main driving member will mesh with the reversing gear, whereby the direction of actuation of the indicating mechanism is reversed.

26. In a calculating machine, the combination with a traveling indicator, of stationary driving mechanism, gearing mechanism for engaging with the mechanism of the indicator, a main driving member for engaging said gearing mechanism, means for normally retaining said main driving mechanism in a normal plane out of engagement with said gearing mechanism, an actuating key, means upon actuation of said key for causing said main driving member to be first brought to another plane into engagement with the gearing mechanism and then rotated to cause rotation of the gearing mechanism and actuation of the indicating mechanism, means for normally locking said gearing mechanism against rotation, and means upon moving said main driving member into engagement with said gearing mechanism for releasing said gearing mechanism.

27. In a calculating machine, the combination with a traveling indicator, of stationary driving mechanism, gearing mechanism for engaging with the mechanism of the indicator, a main driving member for engaging said gearing mechanism, means for normally retaining said main driving mechanism in a normal plane out of engagement with said gearing mechanism, an actuating key, means upon actuation of said key for causing said main driving member to be first brought to another plane into engagement with the gearing mechanism and then rotated to cause rotation of the gearing mechanism and actuation of the indicating mechanism, means for normally locking said gearing mechanism

against rotation, means upon moving said main driving member into engagement with said gearing mechanism for releasing said gearing mechanism, and means for adjusting 5 said gearing mechanism to cause either forward or reverse actuation of the indicator mechanism.

28. In a calculating machine, the combination with a traveling indicator, of stationary driving mechanism, gearing mechanism for said driving mechanism for engagement with the indicator mechanism, a main driving member having rotatable and lateral swinging motion, means for normally locking 10 said gearing mechanism against rotation, means for normally retaining said main driving member out of engagement with said gearing mechanism, a key for said machine, means upon actuation of said key for 15 first causing a lateral swing of said main driving member into engagement with said gearing mechanism, and means for at the same time causing release of the gearing mechanism, continued actuation of said key then 20 causing rotation of said main driving member whereby the indicating mechanism is actuated upon rotation of the gearing mechanism. 25

29. In a calculating machine, the combination with a traveling indicator, of stationary driving mechanism, gearing mechanism for said driving mechanism for engagement with the indicator mechanism, a main driving member having rotatable and 30 lateral swinging motion, means for normally locking said gearing mechanism against rotation, means for normally retaining said main driving member out of engagement with said gearing mechanism, a key for said machine, means upon actuation of said key for 35 first causing a lateral swing of said main driving member into engagement with said gearing mechanism, means for at the same time causing release of the gearing mechanism, continued actuation of said key then 40 causing rotation of said main driving member whereby the indicating mechanism is actuated, and means for adjusting said gearing mechanism and said main driving member to produce either forward or reverse 45 actuation of said indicator mechanism. 50

30. In a calculating machine, the combination with a traveling indicator, of stationary driving mechanism, gearing mechanism for said driving mechanism for engagement with the indicator mechanism, a main driving member having rotatable and lateral swinging motion, means for normally locking said gearing mechanism against 55 rotation, means for normally retaining said main driving member out of engagement with said gearing mechanism, a key for said machine, means upon actuation of said key for first causing a lateral swing of said main driving member into engagement with said 60

gearing mechanism, means for at the same time causing release of the gearing mechanism, continued actuation of said key then causing rotation of said main driving member whereby the indicating mechanism is actuated upon rotation of the gearing mechanism, and means for preventing restoration 70 of an actuated key until actuated its full distance.

31. In a calculating machine, the combination with a traveling indicator, of stationary driving mechanism, gearing mechanism for said driving mechanism for engagement with the indicator mechanism, a main driving member having rotatable 75 and lateral swinging motion, means for normally locking said gearing mechanism against rotation, means for normally retaining said main driving member out of engagement with said gearing mechanism, a key for 80 said machine, means upon actuation of said key for first causing a lateral swing of said main driving member into engagement with said gearing mechanism, means for at the same time causing release of the gearing mechanism, continued actuation of said key then 85 causing rotation of said main driving member whereby the indicating mechanism is actuated upon rotation of the gearing mechanism, means for restoring the depressed 90 key, and means for preventing subsequent depression of said key until fully restored to its normal position.

32. In a calculating machine, the combination with a traveling indicator, of stationary driving mechanism, gearing mechanism for said driving mechanism for engagement with the indicator mechanism, a main driving member having rotatable and lateral swinging motion, means for normally locking 100 said gearing mechanism against rotation, means for normally retaining said main driving member out of engagement with said gearing mechanism, a key for said machine, means upon actuation of said key for first 105 causing a lateral swing of said main driving member into engagement with said gearing mechanism, means for at the same time causing release of the gearing mechanism, continued actuation of said key then causing 110 rotation of said main driving member whereby the indicating mechanism is actuated upon rotation of the gearing mechanism, means for restoring the depressed key to its normal position, means for locking said key against 115 subsequent depression upon failure to restore the key to its normal position, and lever mechanism for releasing said locking means to allow subsequent depression of the key.

33. In a calculating machine, the combination with a traveling indicator, of stationary driving mechanism, gearing mechanism for said driving mechanism for engagement with the indicator mechanism, a main driving member having rotatable and lateral 120

125

swinging motion, means for normally locking said gearing mechanism against rotation, means for normally retaining said main driving member out of engagement with said gearing mechanism, a key for said machine, means upon actuation of said key for first causing a lateral swing of said main driving member into engagement with said gearing mechanism, means for at the same time causing release of the gearing mechanism, continued actuation of said key then causing rotation of said main driving member whereby the indicating mechanism is actuated upon rotation of the gearing mechanism, means for locking said key against restoration unless depressed the proper distance, and lever mechanism for releasing said locking means to allow restoration of the key.

34. In a calculating machine, the combination with a traveling totalizer frame, of a driving gear, driving mechanism intervening between said driving gear and the keys of the machine, a row of totalizer wheels mounted in said totalizer frame and adapted to mesh with the driving gear as the totalizer frame travels, number wheels for said totalizer mechanism, levers for said totalizer mechanism, carry-over mechanism carried by each lever and engaging with adjacent totalizer gears, locking mechanism mounted on said levers and with the totalizer gears, means associated with the driving mechanism for engaging said levers to hold them in locking engagement with the totalizer gears to prevent rotation thereof, and means associated with said driving mechanism and actuated upon depression of a key for engaging the lever associated with the totalizer gear in mesh with the driving gear whereby the locking mechanism is released and rotation of the gear allowed.

35. In a calculating machine, the combination with a traveling totalizer frame, of stationary driving mechanism connected with the keys of the machine, a driving gear for said driving mechanism, a row of totalizer gears mounted in said totalizer frame and adapted to mesh successively with said driving gear as said totalizer frame travels, a number wheel connected with each totalizer gear, a carry-over gear plate secured to each totalizer gear, a locking cam secured to each totalizer gear, a lever mounted in said frame for each totalizer gear, a carry-over pinion pivoted to one end of said lever to be engaged by the corresponding carry-over gear, a locking wheel secured to said carry-over pinion for engagement with the locking cam on the corresponding totalizer gear, a carry-over gear secured to said carry-over pinion for engaging the adjacent totalizer gear, means for normally preventing actuation of said levers whereby the locking mechanism is maintained in engagement and the totalizer gears prevented from rotating, and

means adapted upon actuation of a key for removing the lever and locking mechanism from the totalizer gear in mesh with the driving gear whereby said totalizer gear may be rotated.

36. In a calculating machine, the combination with a totalizer frame adapted to travel horizontally, of a stationary driving gear, driving mechanism intervening between said driving gear and the keys of the machine, a horizontal row of totalizer gears mounted on the totalizer frame and adapted to successively mesh with the driving gear to be rotated upon actuation of a corresponding key, an indicating number wheel associated with each totalizer gear, a carry-over gear plate secured to each totalizer gear, a locking cam secured to each totalizer gear, said cam being in the form of a circular disk having circular peripheral notches, a carry-over pinion for each gear plate, a carry-over gear connected with the carry-over pinion and meshing with the adjacent totalizer gear, a star wheel secured to the carry-over pinion and engaging the locking cam, said star wheel and locking cam preventing rotation of the carry-over pinion by the carry-over gear until a point of said star wheel engages in one of the cam notches, means for normally maintaining the star wheel in engagement with the cam and the carry-over gear in engagement with the adjacent totalizer gear, whereby said adjacent gear wheel is normally locked against rotation when in mesh with the driving gear, and means upon actuation of a key for releasing said adjacent gear from said carry-over gear and locking mechanism, whereby said adjacent gear may be rotated.

37. In a calculating machine, the combination with a totalizer frame adapted to travel horizontally, of a stationary driving gear, driving mechanism intervening between said driving gear and the keys of the machine, a horizontal row of totalizer gears mounted in said totalizer frame and adapted to mesh with the driving gear, a number wheel connected with each totalizer gear, a carry-over gear plate secured to each totalizer gear, a locking cam secured to each totalizer wheel, said cam being in the form of a circular disk having peripheral notches coinciding with the teeth on the carry-over gear plate, a carry-over pinion plate adapted to be actuated by the teeth on the carry-over gear plate, a carry-over pinion secured to the carry-over pinion plate and meshing with the adjacent totalizer gear, a star wheel secured to said carry-over pinion plate, said star wheel having circular notches having a radius equal to that of the locking cam, means for normally retaining the carry-over pinion plate star wheel and carry-over pinion respectively in engagement with the carry-over gear plate, locking cam and ad-

jacent totalizer gear, said star wheel and cam allowing actuation of said carry-over pinion plate only when a point of said star wheel engages in one of the cam slots, and means associated with the driving mechanism and adapted upon actuation of a key to release the carry-over and the locking mechanism from adjacent totalizers whereby the totalizer normally engaged by the carry-over pinion may be actuated by the driving wheel.

38. In a calculating machine, the combination with a totalizer frame adapted to travel horizontally, of a stationary driving wheel, driving mechanism intervening between the driving gear and the keys of the machine, a plurality of totalizer gears mounted in a horizontal row in said totalizer frame and adapted to mesh with the driving gear as the frame travels, a number wheel geared to each totalizer gear, a carry-over gear plate secured to each totalizer gear and provided with suitably spaced carry-over teeth, a locking cam secured to each totalizer gear, said cam being in the form of a circular disk having peripheral notches registering with the carry-over teeth of the carry-over gear plate, a carry-over pinion plate for engaging the carry-over teeth on the totalizer gear, a carry-over pinion for engaging the adjacent totalizer gear, a star wheel secured to the carry-over pinion plate and the carry-over pinion and concentric therewith, said star wheel having peripheral circular notches of the same radius as that of the locking cam, one of said circular notches normally engaging the unbroken surface of the locking cam to prevent actuation of the carry-over mechanism, said carry-over mechanism being free to operate when a point of said star wheel engages in one of the locking cam notches, a lever for supporting star wheel and carry-over mechanism connected therewith, means associated with the driving mechanism for locking said levers to maintain the carry-over and locking mechanism thereon in engagement with the totalizer gears to prevent rotation thereof, and means upon actuation of the driving mechanism for first releasing the lever corresponding to the totalizer gear in mesh with the driving gear whereby said totalizer gear may be subsequently rotated upon further actuation of the driving mechanism to rotate the driving gear.

40. In a calculating machine, the combination with a totalizer frame adapted to travel horizontally, of a stationary driving wheel, driving mechanism intervening between said wheel and the keys of the machine, a plurality of totalizer gears arranged in a row adapted to mesh with the driving gear as the totalizer frame travels, number wheels for said totalizer gears, carry-over and locking mechanism secured to each totalizer gear, levers for supporting carry-over and locking mechanism associated with the locking mechanism on the totalizer gears, means for normally holding said levers in position to retain the carry-over and locking mechanisms in engagement to prevent actuation of the totalizer gears by the driving gear, and means upon actuation of a key and of the driving mechanism for releasing the carry-over and locking mechanisms from the totalizer gear in mesh with the driving gear to allow subsequent rotation thereof.

39. In a calculating machine, the combination with a totalizer frame adapted to travel horizontally, of a stationary driving wheel, driving mechanism intervening between the driving gear and the keys of the machine, a plurality of totalizer gears mounted in a horizontal row in said totalizer frame and adapted to mesh with the driving gear as the frame travels, a number wheel geared to each totalizer gear, a carry-over gear plate secured to each totalizer gear and provided with suitably spaced carry-over teeth, a locking cam secured to each totalizer gear, said cam being in the form of a circular disk

having peripheral notches registering with the carry-over teeth of the carry-over gear plate, a carry-over pinion plate for engaging the carry-over teeth on the totalizer gear, a carry-over pinion for engaging the adjacent totalizer gear, a star wheel secured to the carry-over pinion plate and the carry-over pinion and concentric therewith, said star wheel having peripheral circular notches of the same radius as that of the locking cam, one of said circular notches normally engaging the unbroken surface of the locking cam to prevent actuation of the carry-over mechanism, said carry-over mechanism being free to operate when a point of said star wheel engages in one of the locking cam notches, a lever for supporting star wheel and carry-over mechanism connected therewith, means associated with the driving mechanism for locking said levers to maintain the carry-over and locking mechanism thereon in engagement with the totalizer gears to prevent rotation thereof, and means upon actuation of the driving mechanism for first releasing the lever corresponding to the totalizer gear in mesh with the driving gear whereby said totalizer gear may be subsequently rotated upon further actuation of the driving mechanism to rotate the driving gear.

41. In a calculating machine, the combination with a totalizer frame adapted to travel horizontally, of a stationary driving gear, driving mechanism intervening between said driving gear and the keys of the machine, a plurality of totalizer gear wheels mounted in a horizontal row and adapted to mesh with the driving gear as the totalizer frame travels, an indicating number wheel for each totalizer gear, carry-over mechanism and locking mechanism secured to each totalizer gear, associate, carry-over and locking mechanism for engaging with the carry-

over and locking mechanism on the totalizer gears, levers upon which the associate locking mechanism is carried, means for normally retaining said levers in position to hold the associate mechanism in engagement with the carry-over and locking mechanism on the totalizer gears to prevent rotation of said gears, means upon actuation of a key and the driving mechanism for moving a lever to carry the associate mechanism out of engagement whereby the corresponding totalizer gear engaged by the driving gear may be rotated, and means for preventing displacement of the associate mechanism when thus carried out of engagement.

42. In a calculating machine, the combination with a totalizer frame adapted to travel horizontally, of a stationary driving gear, driving mechanism intervening between said driving gear and the keys of the machine, a plurality of totalizer gear wheels mounted in a horizontal row and adapted to mesh with the driving gear as the totalizer frame travels, an indicating number wheel for each totalizer gear, carry-over mechanism and locking mechanism secured to each totalizer gear, associate, carry-over and locking mechanism for engaging with the carry-over and locking mechanism on the totalizer gears, levers upon which the associate locking mechanism is carried, means for normally retaining said levers in position to hold the associate mechanism in engagement with the carry-over and locking mechanism on the totalizer gears to prevent rotation of said gears, means upon actuation of a key and the driving mechanism for moving a lever to carry the associate mechanism out of engagement whereby the corresponding totalizer gear engaged by the driving gear may be rotated, and a detent associated with the adjacent lever for preventing displacement of the associate mechanism when thus moved out of engagement.

43. In a calculating machine, the combination with a traveling indicator, of stationary driving mechanism, gearing mechanism for engaging with the mechanism of the indicator, a main driving member for engaging said gearing mechanism, means for normally retaining said main driving member out of engagement with said gearing mechanism, an actuating key, means upon actuation of said key for causing said main driving member to be first moved laterally into engagement with the gearing mechanism and then rotated to cause rotation of the gearing mechanism and actuation of the indicating mechanism, means for normally locking said gearing mechanism against rotation, and means upon moving said main driving member into engagement with said gearing mechanism for releasing said gearing mechanism to allow subsequent rotation thereof by the rotating driving member.

44. In a calculating machine, the combination with indicating mechanism, of a main driving member for actuating said mechanism, said driving member being normally out of driving relation with said indicating mechanism, means upon actuation of a key of the machine for causing first said driving member to be moved laterally into driving relation with the indicating mechanism and further actuation of the key causing rotation of the driving member and of the indicating mechanism engaged thereby, locking means for preventing restoration of the key and of the driving member to the normal position until said key has been actuated its full distance, and lever mechanism for releasing said locking means to allow said restoration.

45. In a calculating machine, the combination with indicating mechanism, of a main driving member for actuating said mechanism, said driving member being normally out of driving relation with said indicating mechanism, means upon actuation of a key of the machine for causing first said driving member to be moved laterally into driving relation with the indicating mechanism and further actuation of the key causing rotation of the driving member and of the indicating mechanism engaged thereby, locking means for preventing movement of said driving member to its normal position out of driving relation with the indicating mechanism until the key has been actuated its full stroke, and lever mechanism for releasing the locking means.

46. In a calculating machine, the combination with indicating mechanism, of driving mechanism, gearing mechanism for engaging the indicating mechanism, a main driving member for the driving mechanism, said main driving member being normally out of meshing engagement with the gearing mechanism, detent mechanism normally engaging the gearing mechanism to prevent rotation thereof, an actuating key, and means upon actuation of said key for causing said main driving member to be moved laterally into mesh with the gearing mechanism and causing at the same time release of the detent mechanism, further actuation of the key causing rotation of the driving member and the gearing mechanism.

47. In a calculating machine, the combination with indicating mechanism, of actuating gear wheels for said mechanism, a driving gear wheel for engaging said mechanism gear wheels, a main driving member normally displaced to be prevented from meshing with said driving gear wheel upon rotation thereof, keys for said machine, and means upon actuation of a key for causing the main driving member to be first moved into a position where it may mesh with said driving gear wheel and then to cause rotation of said

driving gear wheel and of the indicating mechanism gear wheels.

48. In a calculating machine, the combination with mechanism for indicating calculations, of actuating gear wheels for said mechanism, a driving member normally out of driving relation with said gear wheels, keys for said machine, and means upon actuation of a key for causing said driving member to be first moved laterally into driving relation with the gear wheels and then to cause rotation thereof and of said gear wheels.

49. In a calculating machine, the combination with mechanism for indicating calculations, of actuating gear wheels for said mechanism, a driving member normally out of meshing relation with said gear wheels, keys for the machine, and means upon actuation of a key for causing the driving member to be first moved laterally into meshing relation with the gear wheels and then to be rotated to cause rotation of the gear wheels.

50. In a calculating machine, the combination with mechanism for indicating calculations, of actuating gear wheels for said mechanism, a driving member normally out of meshing relation with said gear wheels, keys for the machine, and means upon actuation of a key for causing the driving member to be first swung laterally into meshing relation with the gear wheels and then to be rotated to cause rotation of the gear wheels.

51. In a calculating machine, the combination with indicating mechanism having actuating gear wheels, of a driving member normally out of meshing relation with said gear wheels, keys for the machine, and means upon actuation of a key for causing the driving member to be first moved laterally into meshing relation with the gear wheels, then to be rotated to cause rotation of the gear wheels, and then to be moved laterally to its normal position out of meshing relation.

45 52. In a calculating machine, the combination with indicating mechanism having actuating gear wheels, of a driving member normally out of meshing relation with said gear wheels, keys for the machine, means upon first actuation of a key for causing the driving member to be moved laterally into meshing relation with the gear wheels, means upon further actuation of the key for causing rotation of the driving member and of the gear wheels, and means upon release of the key for causing said driving member to be moved laterally to its normal position out of meshing relation with the gear wheels.

53. In a calculating machine, the combination with indicating mechanism having actuating gear wheels, of a driving member normally held out of line with said actuating gear wheels, keys for the machine, means upon actuation of a key for first causing the driving member to be moved into line with

said actuating gear wheels, means upon further actuation of the key for causing rotation of the driving member and the gear wheels, means upon restoration of the key to its normal position for causing said driving member to be moved out of line back to its normal position, and means for preventing restoration of the actuating key until said key has been actuated a predetermined distance to cause a predetermined amount of rotation of the driving member and gear wheels.

54. In a calculating machine, the combination with indicating mechanism, having actuating gear wheels, of a driving member normally held out of line with said actuating gear wheels, keys for the machine, means upon actuation of a key for first causing the driving member to be moved into line with said actuating gear wheels, means upon further actuation of the key for causing rotation of the driving member and the gear wheels, means upon restoration of the key to its normal position for causing said driving member to be moved out of line back into its normal position, and ratchet mechanism for preventing restoration of the key until said key has been actuated a predetermined distance to cause a predetermined amount of rotation of the driving member and gear wheels.

55. In a calculating machine, the combination with indicating mechanism having actuating gear wheels, of a driving member normally out of meshing relation with said gear wheels, keys for the machine, means upon actuation of a key for first causing the driving member to be moved into meshing relation with the gear wheels, means upon further actuation of the key for causing rotation of the driving member and the gear wheels, means upon restoration of the key to its normal position for causing said driving member to be moved from meshing relation into its normal position, ratchet mechanism for preventing restoration of the actuating key until said key has been actuated a predetermined distance to cause a predetermined amount of rotation of the driving member and gear wheels, and lever mechanism for releasing the ratchet mechanism to allow restoration of the key.

56. In a calculating machine, the combination with indicating mechanism having actuating gear wheels, of a driving member for engaging said gear wheels, keys for the machine, means upon actuation of a key for causing rotation of the driving member gear wheels, and ratchet means for preventing restoration of the key to its normal position until said key has been actuated a predetermined distance to cause a predetermined amount of rotation of the driving member and lever mechanism for releasing the ratchet means to allow restoration of the key.

57. In a calculating machine, the combination with indicating mechanism, of a driving member, keys for the machine, means upon actuation of a key for causing rotation of the driving member, locking means for preventing subsequent actuation of said key until said key has been entirely restored to its normal position and lever mechanism for releasing the locking means to allow restoration of said key.

58. In a calculating machine, the combination with indicating mechanism, of a driving member, keys for the machine, means upon actuation of a key for causing rotation of the driving member and of the gear wheels, ratchet mechanism for preventing subsequent actuation of said key until said key has been entirely restored to its normal position and lever mechanism for releasing the ratchet mechanism to allow actuation of said key.

59. In a calculating machine, the combination with indicating mechanism, of a driving member normally out of driving relation with the indicating mechanism, keys for the machine, means upon depression of a key for causing lateral motion of the driving member into driving relation with the indicating mechanism, means upon further actuation of the key for causing rotation of the driving member and actuation of the indicating mechanism, means upon restoration of the key to its normal position tending to cause return of the driving member to its normal position out of driving relation with the indicating mechanism, and means for preventing restoration of said key until said key has been actuated a predetermined distance to cause a predetermined amount of rotation of the driving member.

60. In a calculating machine, the combination with indicating mechanism, of a driving member normally out of driving relation with said indicating mechanism, keys for the machine, means upon actuation of a key for causing the driving member to be first moved into driving relation with the indicating mechanism and then rotated to cause actuation of the indicating mechanism, and means for preventing return of the driving member to its normal position until said key has been actuated a predetermined distance to cause a predetermined amount of rotation of the driving member.

55 61. In a calculating machine, the combination with indicating mechanism having actuating gear wheels, of a forward driving gear adapted to mesh with the indicating mechanism gear wheels, a reverse gear in mesh with said forward gear, a main driving gear wheel normally in mesh with the forward driving gear whereby actuation of the main driving gear will cause forward actuation of the indicating mechanism, and means for moving both the reverse gear and the

main driving gear to disengage the main driving gear from the forward driving gear and to bring the main driving gear into mesh with the reverse gear whereby upon actuation of the main driving member the indicating mechanism will be actuated in reverse direction.

62. In a calculating machine, the combination with indicating mechanism having actuating gear wheels, of a stationary forward driving gear adapted to mesh with the indicating mechanism gear wheels, a reverse gear in mesh with the forward gear, a main driving gear normally out of meshing engagement with the forward or reverse gears, keys for the machine, means upon actuation of a key for causing first lateral motion of the main driving member into meshing relation with the forward gear and then causing rotation of the main driving member, means upon release of the actuating key for causing the main driving member to be disconnected from the forward driving member and returned laterally to its normal position, and means for moving the main driving member so that upon subsequent actuation of a key said driving member will be first brought into meshing relation with the reverse gear whereupon continued actuation of said key causes reverse actuation of the indicating mechanism.

63. In a calculating machine, the combination with indicating mechanism having actuating gear wheels, of a forward driving gear for meshing engagement with said actuating gear wheels, a reverse gear in mesh with the forward driving gear, a main driving member, a shaft to which said main driving member is pivoted to rotate therewith and to have swinging motion thereon, keys for the machine, means upon actuation of a key for causing said main driving member to be swung into meshing relation with the driving gear and then causing rotation of the shaft and of the main driving member, restoration of the key to its normal position causing return of the main driving member to its normal position, means for moving the reverse gear and the shaft in said main driving member to change the relative positions of the main driving member and driving gears whereby subsequent actuation of the key will cause lateral motion of the main driving member into meshing engagement with only the reverse gear whereby continued actuation of the key causes reverse actuation of the indicating mechanism.

64. In a calculating machine, the combination with indicating mechanism having actuating gear wheels and number wheels associated therewith, of a driving member for causing actuation of the gear wheels and number wheels, said driving member being normally out of driving relation with the actuating gear wheels, keys for the machine,

means upon first actuation of a key for moving the driving member into driving relation with the actuating gears, means upon further actuation of the key for causing rotation of the driving member and actuation of the gears, means for restoring the key to its normal position after said key has been moved the full length of its stroke, means after the key has been actuated through its whole stroke for returning the driving member to its normal position out of driving relation with the gear wheels, means for preventing restoration of the key and of the driving member to their normal positions when the key has been actuated only to an intermediate point of its stroke, and means for releasing the key from its intermediate position to allow restoration thereof and to allow restoration of the driving member and of the engaged indicating mechanism members to their normal positions.

65. In a calculating machine, the combination with indicating mechanism, of driving mechanism connected with the keys of the machine, a driving gear for said driving mechanism, a row of totalizer gears for said indicating mechanism disposed to mesh with said driving gear, a number wheel connected with each totalizer gear, a carryover gear plate secured to each totalizer gear, a locking cam secured to each totalizer gear, a frame associated with each totalizer gear, a carryover pinion pivoted to one end of said frame to be engaged by the corresponding carryover gear, a locking wheel secured to said carryover pinion for engagement with the locking cam of the corresponding totalizer gear, a carryover gear secured to said carryover pinion for engaging the adjacent totalizer gear, said locking wheel normally engaging the locking cam to prevent rotation of the carryover gear, and means at predetermined points during the rotation of the totalizer gear and locking cam for releasing the locking wheel to allow rotation of the carryover gear and consequent rotation of an adjacent totalizer gear.

66. In a calculating machine, the combination with a frame in which is mounted a row of totalizer gears, of driving mechanism connected with the keys of the machine, a driving member for the driving mechanism adapted to mesh with the totalizer gears, a number wheel connected with each cyclometer gear, a carryover gear plate secured to each totalizer gear, a locking cam secured to each totalizer gear, said cam wheel being in the form of a circular disk having peripheral notches coinciding with the teeth on the carryover gear plate, a carryover pinion plate adapted to be actuated by the teeth on the carryover gear plate, a carryover pinion secured to the carryover pinion plate and meshing with the adjacent totalizer gear, and a star wheel secured to the carryover pinion plate, said star wheel having circular notches

for engaging the peripheral edge of the locking cam, said carryover pinion being prevented from rotation when a notch of the star wheel engages the unbroken periphery of the locking cam but adapted to be rotated when a point of the star wheel engages in one of the cam slots whereby the adjacent gear wheel is actuated at predetermined points during the rotation of the first gear wheel.

67. In a calculating machine, the combination with indicating mechanism comprising a row of totalizer gear wheels, of driving mechanism connected with the keys of the machine and having a driving member adapted to mesh with the gear wheels, a carryover gear plate secured to each gear wheel, a locking cam secured to each gear wheel, a carryover gear pivoted to said lever for meshing with the adjacent totalizer gear, a carryover pinion secured to said carryover gear to be engaged by the corresponding carryover gear plate, a locking wheel secured to said carryover gear for engagement with the locking cam, means for normally retaining the lever frame in position to hold the locking wheel in engagement with the locking cam whereby the adjacent totalizer wheel is locked against rotation, and means upon engagement of said adjacent totalizer gear wheel with the driving member for causing actuation of the lever frame to release the locking mechanism whereby said adjacent totalizer gear may be rotated.

68. In a calculating machine, the combination with indicating mechanism containing a row of totalizer gears, of driving mechanism associated with the keys of the machine and having a driving gear for meshing with the totalizer gears, a locking cam secured to each totalizer gear, said locking cam being in the form of a circular disk, a lever frame for each totalizer gear, a pinion pivoted to said frame engaging the adjacent totalizer gear, a locking wheel secured to said pinion and having circular notches about its periphery for engaging the periphery of the locking cam, means for normally retaining the lever frame in position to hold the locking wheel in engagement with the locking cam to lock the adjacent totalizer gear against rotation, and means upon engagement of the adjacent totalizer gear with the driving gear for causing movement of said lever frame to release the locking wheel from the locking cam whereby said adjacent totalizer gear may be rotated.

69. In a calculating machine, the combination with indicating mechanism containing a row of totalizer gears, of driving mechanism connected with the keys of the machine and having a driving gear for meshing with the totalizer gears, a locking cam in the form of a circular disk secured to each cyclometer gear, a lever associated with each totalizer gear, a pinion pivoted to said lever for mesh-

ing with the adjacent totalizer gear, a locking wheel secured to said pinion having circular grooves in its periphery for engaging the peripheral surface of the locking cam, an extension from each lever, a stationary bar for engaging said extensions to hold the levers in position to engage the locking wheels with the locking cam whereby the totalizer gears are prevented from being rotated, and mechanism adapted upon actuation of a key and upon engagement of the driving gear with a totalizer gear to move the proper lever to disengage the pinion from said totalizer gear whereby said totalizer gear may be rotated.

70. In a calculating machine, the combination with a traveling totalizer frame containing a row of totalizer gear wheels, of stationary driving mechanism having a driving gear for successively meshing with the totalizer gears, a locking cam secured to each totalizer gear in the form of a circular plate, a lever associated with each totalizer gear, a pinion pivoted to each lever for engagement with the adjacent totalizer gear, a locking wheel secured to the pinion having circular notches about its periphery for engaging the circular periphery of the corresponding locking cam, a stationary bar, extensions from the levers engaged by said bar to hold said levers in position to maintain engagement of the locking wheel and locking cam whereby rotation of the totalizer gears is prevented, and means when a totalizer gear is brought into meshing relation with the driving member for causing movement of the proper lever to disengage the locking mechanism whereby said totalizer gear may be rotated.

71. In a calculating machine, the combination with indicating mechanism, of a driving member, means tending to hold said driving member in a normal position out of driving relation with indicating mechanism to be actuated, means upon actuation of a key for first causing the driving member to be moved into driving relation with the mechanism to be actuated and then to drive said mechanism, locking means for preventing restoration of the key until completely actuated, the driving member upon such incomplete actuation of the key causing incomplete actuation of engaged indicating mechanism, and lever mechanism for releasing the key to allow the driving member to restore the engaged indicating mechanism to its normal position.

72. In a calculating machine, the combination with indicating mechanism, of a driving member, means tending to hold said driving member in a normal position out of driving relation with indicating mechanism to be actuated, means upon actuation of a key for first causing the driving member to be moved into driving relation with the mechanism to be actuated and then to drive said mechanism, locking means for preventing restoration

of the key until completely actuated, the driving member upon such incomplete actuation of the key causing incomplete actuation of engaged indicating mechanism, and lever mechanism for releasing the key to allow the driving member to restore the engaged indicating mechanism to its normal position, and means for preventing return of the driving member to its normal position until said indicating mechanism has been fully restored.

73. In a calculating machine, the combination with indicating mechanism, of a main driving member, capable of lateral movement and adapted to drive said indicating mechanism when in one lateral position and to not drive it when in another lateral position; and means upon actuation of a key for first moving said member into position for driving the indicating mechanism and then causing actuation of the indicating mechanism.

74. In a calculating machine, the combination of indicating mechanism a rotary member for operating it, a driving member, said rotary and driving members being normally in different planes, and means upon actuation of a key for causing first movement of the members into the same plane, and then rotation thereof.

75. In a calculating machine, the combination with indicating mechanism, of a driving member having rotatable and swinging motion, gearing mechanism between the indicating mechanism and driving member, means for moving gearing mechanism to one position so that the driving member upon actuation of a key will swing into engagement to cause forward rotation of the indicating mechanism, and to another position so that the driving member will swing into engagement to cause reverse actuation of the indicating mechanism.

76. In a calculating machine, the combination with indicating mechanism, of a main driving member for causing actuation of indicating mechanism, said member being normally out of driving relation with said mechanism, means for causing lateral motion to another plane of said member to bring said member into engagement with said mechanism, and means thereafter for rotating said member to cause actuation of engaging mechanism part.

77. In a calculating machine, the combination with indicating mechanism having gear wheels, of a main driving member having both lateral and rotational movement, a forward driving gear for meshing with the indicating gear wheel, a reverse gear wheel having meshing engagement with said forward gear, keys for the machine, means upon actuation of a key for causing first lateral motion of the main driving member into mesh with the forward gear and then rotational movement to cause rotation of the forward wheel and indicating mechanism gear wheels, and

means for moving the reverse gear and driving gear laterally whereby the driving member is carried from meshing engagement with the main driving gear and into meshing engagement with the reverse gear.

78. In a calculating machine, the combination with mechanism for indicating calculations, of actuating gear wheels for said mechanism, a driving gear wheel for engaging said mechanism gear wheels, a main driving member normally out of mesh with said driving gear, keys for said machine, and means upon first actuation of a key for the said main driving member to be swung to another plane into mesh with said driving gear, and upon further actuation of said key to cause rotation of said driving gear and of the mechanism gears.

79. In a calculating machine, the combination with indicating mechanism, of a driving member normally in a plane out of driving relation with the indicating mechanism, and means operated upon actuation of a key for swinging said driving member to another plane into driving relation with the indicating mechanism.

80. In a calculating machine, the combination with indicating mechanism to be actuated, of a rotary member for actuating it, a swinging driving member, said rotary and driving members being normally in different planes, and means operable upon actuation of a key for first swinging the driving member into the plane of the rotary member, and then rotating it.

81. In a calculating machine, the combination with indicating mechanism, of driving means adapted upon actuation of keys to operate the indicating mechanism, means for locking the actuated keys and engaged indicating mechanism against restoration upon incomplete actuation of the keys, and lever mechanism adapted upon actuation to release the locking means from the keys and indicating mechanism to allow restoration of the key and to restore the indicating mechanism to its normal position.

82. In a calculating machine, the combination with indicating mechanism, of a driving gear normally disposed in an inclined plane, and means operable upon actuation of a key of the machine for first moving the gear to a vertical plane and then rotation thereof to operate the engaged indicating mechanism.

83. In a calculating machine, the combination with indicating mechanism, of a driving member adapted to be swung from a normal inclined plane to a vertical plane into driving relation with the indicating mechanism.

84. In a calculating machine, the combination with indicating mechanism, of a main actuating wheel pivoted to the machine frame for engagement with the indicating mechanism, a segmental gear having rotational movement and lateral swinging move-

ment to be normally swung out of driving relation with the actuating wheel, mechanism associated with the segmental gear and with the machine keys adapted upon actuation of a key to first swing the key into driving relation with the actuating wheel and then to rotate the segmental gear to cause actuation of the indicating mechanism, locking means for preventing restoration of the key unless sufficiently actuated, and lever mechanism for releasing said locking mechanism, said lever mechanism being also associated through intervening mechanism with the segmental gear to hold said gear in driving relation with the actuating wheel until said segmental gear has been returned to its normal position upon restoration of the released key.

85. In a calculating machine, the combination with totalizer mechanism, of driving mechanism normally out of driving engagement therewith, mechanism connected with the driving mechanism and with the keys of the machine and adapted upon depression of a key to first move the driving mechanism into driving relation with the totalizer mechanism and then to cause actuation of the driving mechanism to actuate the totalizer mechanism, locking means for preventing restoration of a key until said key is depressed its full distance, means for releasing said locking mechanism, means independent of the keys for reversing the driving mechanism to restore it to its normal position, and means for preventing said driving mechanism from moving out of driving relation with the totalizer mechanism upon reversal thereof to its normal position.

86. In a calculating machine, the combination with indicating mechanism, of driving mechanism therefor normally out of driving relation with the indicating mechanism, means upon actuation of a key of the machine for causing the driving mechanism to be brought first into driving relation with the indicating mechanism, locking means for preventing restoration of an actuated key until said key has been moved a required distance, and correcting mechanism adapted upon actuation to release the locking mechanism, and to lock the driving mechanism in driving relation with the indicating mechanism and to reverse the driving mechanism to its initial driving position, and then to release the driving mechanism from driving relation with the indicating mechanism.

87. In a calculating machine, the combination with totalizer mechanism, of keys connected with the totalizer mechanism to cause operation thereof, pawl and ratchet mechanism for each key for preventing movement of the key in one direction until it has been moved the full required distance in the other direction, and a common means for releasing the keys from the pawl and ratchet mechanism.

88. In a calculating machine, the combination with totalizer mechanism having a series of driving gears, of keys, mechanism for transmitting the movement of said keys to the totalizer gears, common locking means for all the keys for preventing restoration of any key or keys until there has been complete actuation of said key for keys and of the totalizer gears driven thereby, and a hand lever for actuating the locking means to release a partially actuated key or keys.

89. In a calculating machine, the combination with calculating mechanism, of keys, mechanism for transmitting the motion of the keys to the calculating mechanism, ratchet mechanism for each key, a common pawl for the ratchet mechanisms, the adjustment of the pawl and ratchet mechanism being such that when a key is only partially moved in one direction it will be locked against movement in the opposite direction, and hand operable means for moving the pawl frame to release keys which have been locked thereby.

90. In a calculating machine, the combination with calculating mechanism, of keys, mechanism for transmitting the motion of the keys to the calculating mechanism, ratchet mechanism for each key, a common pawl frame for the ratchet mechanisms, the adjustment of the pawl mechanism being such as to prevent return of a key or keys in one direction when only partially operated in the opposite direction, and hand lever mechanism for moving the pawl frame to release keys from any locked position.

91. In a calculating machine, the combination with totalizer mechanism, of keys, driving mechanism for transmitting the movement of a key to the totalizer mechanism, said driving mechanism being normally out of driving connection with the totalizer mechanism, a universal shaft, lever mechanism connected with said shaft and with the driving mechanism, ratchet mechanism for each key, pawl mechanism for each key supported from the universal shaft, movement of a key a short distance in one direction causing engagement of its ratchet mechanism with the pawl mechanism to cause rotation of the universal shaft and operation of the lever mechanism to move the driving mechanism into driving connection with the totalizer mechanism, means adapted upon further movement of said key for causing operation of the driving mechanism to actuate the totalizer mechanism, said pawl and ratchet mechanism locking said key against return until it has been depressed its full distance, and said universal shaft being held in its rotated position by the pawl and ratchet mechanism so that the driving mechanism is held in driving connection with the totalizer mechanism throughout the full stroke of the key, whereby error is prevented.

92. In a calculating machine, the combination with totalizer mechanism, of keys, driving mechanism for transmitting the movement of a key to the totalizer mechanism, said driving mechanism being normally out of driving connection with the totalizer mechanism, a universal shaft, lever mechanism connected with said shaft and with the driving mechanism, ratchet mechanism for each key, pawl mechanism for each key supported from the universal shaft, movement of a key a short distance in one direction causing engagement of its ratchet mechanism with the pawl mechanism to cause rotation of the universal shaft and operation of the lever mechanism to move the driving mechanism into driving connection with the totalizer mechanism, means adapted upon further movement of said key for causing operation of the driving mechanism to actuate the totalizer mechanism, said pawl and ratchet mechanism locking said key against return until it has been depressed its full distance, said universal shaft being held in its rotated position by the pawl and ratchet mechanism so that the driving mechanism is held in driving connection with the totalizer mechanism throughout the full stroke of the key, and hand operable means for rotating the universal shaft in a direction to release the pawl mechanism from the ratchet mechanism of a partially depressed key and in such direction that the driving mechanism will be held in driving connection with the totalizer mechanism while the released key returns to its normal position, whereby the partial entry in the totalizer mechanism upon depression of the key is withdrawn upon restoration of the key.

93. In a calculating machine, the combination with totalizer mechanism, of keys, receiving wheels for the totalizer mechanism, carryover and locking wheels normally in engagement with the receiving wheels to prevent operation thereof, pivoted arms carrying the carryover and locking pinions, driving mechanism for transmitting the movement of the keys to the totalizer receiving wheels, and actuating means operated at the beginning of the down stroke of a key to rotate one of the arms to release the carryover and locking pinion supported thereby from the receiving wheel which is to be rotated upon further depression of the key.

94. In a calculating machine, the combination with totalizer mechanism, of keys, receiving wheels for the totalizer mechanism, carryover and locking wheels normally in engagement with the receiving wheels to prevent operation thereof, pivoted arms carrying the carryover and locking pinions, driving mechanism for transmitting the movement of the keys to the totalizer receiving wheels, actuating means operated at the beginning of the down stroke of a key to rotate

one of the arms to release the carryover and locking pinion supported thereby from the receiving wheel which is to be rotated upon further depression of the key, and means for causing relative movement between the totalizer mechanism and the driving mechanism whereby the supporting arms are rotated *seriatim*.

95. In a calculating machine having keys, 10 the combination of a traveling totalizer frame, a row of totalizer wheels mounted in said totalizer frame, a driving gear adapted to be engaged *seriatim* by the totalizer wheels as the totalizer frame travels, levers 15 pivoted in the totalizer frame, carryover and locking pinion mechanism pivoted on each arm and normally held in locking engagement with the corresponding totalizer wheel, and means actuated upon depression of a key 20 for engaging the lever associated with the totalizer gear in mesh with the driving gear whereby the locking mechanism is released and rotation of the gear allowed.

96. In a calculating machine, the combination with totalizer mechanism having receiving wheels, carryover wheels in engagement with the receiving wheels, supporting arms for the carryover wheels normally locked against rotation to hold the carryover wheels 25 in locking engagement with the receiving wheels, keys for the machine, driving mechanism for transmitting the movement of the keys to the driving wheels, means for causing relative movement between the totalizer 30 mechanism and the driving mechanism whereby said driving mechanism may engage *seriatim* with the receiving wheels, means for unlocking each of the arms when the corresponding receiving wheel is in position to be 35 actuated by the driving mechanism, and means controlled by the depression of the key for swinging a released arm to move the carryover wheel supported thereby away from the receiving wheel in advance of the 40 receiving wheel about to be actuated.

97. In a calculating machine, the combination of indicating mechanism, numeral keys, a driving member, common to all of the keys for actuating said indicating mechanism, 50 means tending to hold said driving member in a normal position laterally out of driving relation with said indicating mechanism, means upon actuation of a key for first causing the driving member to be moved laterally 55 into driving relation with the mechanism to be actuated and to drive said member, locking means for preventing the restoration of the key until completely actuated, the driving member upon incomplete actuation of the 60 key causing incomplete actuation of the indicating mechanism, and a lever mechanism for releasing the key to allow the driving member to restore the indicating mechanism to its previous condition.

98. In a calculating machine, a totalizer,

an operating shaft for operating it, a set of arms extending radially from said shaft at different angles, a projection on each of said arms, a key driven cam for each of said arms adapted to contact the projection thereon for operating said shaft and an extension on each of said cams for preventing overthrow of the shaft.

99. In a calculating machine, a totalizer, an operating shaft for operating it, a set of arms extending radially from said shaft at different angles, a projection on each of said arms, a key driven cam for each of said arms adapted to contact the projection thereon for operating said shaft and an extension on each of said cams adapted to contact said extensions for preventing overthrow of said shaft.

100. In a calculating machine, a totalizer, an operating shaft, a swinging and rotary segment on said shaft, operative on said totalizer when in one lateral position and non operative thereon when in another lateral position, means for swinging said segment to operative and non operative position, and means for rotating said shaft, said means including a set of arms extending radially from said shaft at different angles, a projection on each of said arms, a key driven cam for each of said arms adapted to contact the projection thereon for operating said shaft and an extension on each of said cams for preventing overthrow of said shaft.

101. In a key operated calculating machine, the combination with the keys and key connections of a series of carrying gears, a series of auxiliary carrying pinions adapted to move bodily toward and from said carrying gears for connecting the latter in pairs and releasing them, means for urging said pinions toward said gears, and an adjustable stop for limiting the movement of the pinions toward said gears for preventing the pinions from bearing too hard upon them.

102. In a key operated calculating machine, the combination with the keys and key connections of a series of carrying gears, a series of auxiliary carrying pinions, supports for said pinions, adapted to move them toward and from said gears, said supports being urged to move said pinions toward said gears, and an adjustable stop for each of said supports for limiting the movement thereof.

103. In a key operated calculating machine, the combination with the keys and key connections of a series of carrying gears, a series of auxiliary carrying pinions, pivoted levers for supporting said pinions, adapted to move them toward and from said gears, springs acting upon said levers to urge them to move said pinions toward said gears, and an adjustable stop for each lever for limiting the movement thereof.

104. In a calculating machine, a series of

carrying gears, a series of auxiliary carrying pinions, pivoted levers for supporting said pinions, adapted to move them toward and from said gears, said levers being spring urged to move said pinions toward said gears and key operated means adapted to act upon said levers for moving them to withdraw said pinions from said carrying gears.

105. In a key operated calculating machine, a traveling totalizer including a series of carrying gears, a series of auxiliary carrying pinions for connecting one carrying gear with another, pivoted members for supporting said pinions adapted to move them toward and from said gears and springs acting upon said pivoted members to move said pinions toward said gears, and a member operated by the keys of the machine adapted to operate upon said pivoted members one at a time for withdrawing the supported pinion from its carrying gears.

106. In a key operated calculating machine, a traveling totalizer including a series of carrying gears, a series of auxiliary carrying pinions for connecting one carrying gear with another, pivoted members for supporting said pinions adapted to move them toward and from said gears and springs acting upon said pivoted members to move said pinions toward said gears, and an adjustable stop for each lever for limiting the movement thereof, in combination with a member operated by the keys of the machine adapted to operate upon said pivoted members one at a time for withdrawing the supporting pinion from its carrying gears.

107. In a key operated calculating machine the combination with the keys and key connections of carrying gears, auxiliary carrying pinions bodily movable toward and from said gears for connecting them in pairs and disconnecting them, pivoted levers arranged side by side for moving said pinions bodily, and holding means on each of said levers for preventing accidental rotation of the pinion on the next adjacent lever when said last mentioned pinion is out of engagement with its carrying wheel.

108. In a key operated calculating machine the combination with the keys and key connections of carrying gears, auxiliary carrying pinions bodily movable toward and from said gears for connecting them in pairs and disconnecting them, pivoted levers arranged side by side for moving said pinions bodily, and a tooth on each of said levers for preventing accidental rotation of the pinion in the next adjacent lever when said last mentioned pinion is out of engagement with its carrying wheel.

109. A key operated calculating machine including a totalizer having wheels with spaces between them for pointing-off, keys for operating said wheels, and means for pre-

venting the operation of the keys at such 65 pointing-off spaces.

110. In a calculating machine, the combination of a totalizer having wheels with spaces between them for pointing-off, keys, key connections for actuating the totalizer, and means for preventing the operation of the keys at such pointing-off spaces.

111. In a recording calculating machine, the combination of printing mechanism, keys for operating the same and means for preventing the operation of the keys at certain 75 spaces or stations corresponding to pointing-off points in the written number, whereby a figure cannot be printed in such pointing-off spaces.

112. In a recording calculating machine the combination of a printing mechanism, a totalizer, key connections common to both of them, said key connections and totalizer being relatively movable for determining the 85 ordinal value of the key struck and means located in correspondence with some of the ordinal places for preventing at such points the operation of said key connections.

113. In combination, a master gear wheel, 90 differential mechanism for operating the same; a totalizer adapted to be operated in its different ordinal places successively by said master wheel, said totalizer having pointing-off points therein formed by spacing the totalizer parts into groups; and locking means in the totalizer at the pointing-off points therein for preventing the rotation of the master wheel at those points and thereby calling attention of the operator in case operation at 95 those points is attempted.

114. In combination a master gear wheel, keys, positive gear connections between them so constructed that when the master wheel is held the keys cannot be depressed; a totalizer adapted to be operated in its different 105 ordinal places successively by said master wheel, said totalizer having pointing-off points therein formed by spacing the totalizer parts into groups; and locking means in the totalizer at the pointing-off points therein for preventing the rotation of the master wheel at those points and thereby calling attention of the operator in case operation at 110 those points is attempted.

115. In a calculating machine having a totalizer with pointing-off spaces therein, and positive geared key connections for operating the totalizer; means for preventing the depression of the keys at the pointing-off spaces 120 in the totalizer.

116. In a recording calculating machine, keys, printing mechanism and calculating mechanism including a rotatable shaft for operating said calculating mechanism, said 125 printing mechanism being operated by said keys, and said shaft normally being operated by them, said shaft being also rotatable to a

position where it is inoperable by said keys to thereby permit the machine to print without calculating.

117. In a recording calculating machine, 5 keys, printing mechanism and calculating mechanism including a rotatable shaft for operating said calculating mechanism, said printing mechanism being operated by said keys, and said shaft normally being operated by them, said shaft being also rotatable to a position where it is inoperable by said keys to thereby permit the machine to print without calculating, and means for rotating said shaft to, and holding it in, the position where 15 it is inoperable by said keys.

118. In a recording calculating machine, 20 keys, printing mechanism and calculating mechanism including a rotatable shaft for operating said calculating mechanism, said printing mechanism being operated by said keys, and said shaft normally being operated by them, said shaft being also rotatable to a position where it is inoperable by said keys to thereby permit the machine to print 25 without calculating, and a hand lever for rotating said shaft to the position where it is inoperable by said keys.

119. In a recording calculating machine, 30 printing mechanism, calculating mechanism and a key common to both for operating them, said calculating mechanism including a rotatable operating shaft, said shaft having a projection thereon, and mechanism operated by said key for engaging said projection 35 to rotate said shaft forwards from normal position to thereby operate the calculating mechanism, and means for rotating said shaft to where its projections cannot be engaged, the machine being thereby rendered 40 capable of printing without calculating.

120. In a recording calculating machine, 45 printing mechanism, calculating mechanism and keys common to both for operating them, said calculating mechanism including a rotatable shaft for operating the remainder of the calculating mechanism when rotated in a forward direction, and said shaft having a series of projections arranged at different angles thereon, and cam mechanism operated 50 by said keys adapted to engage said projections to rotate said shaft forward from normal position, and manually operated means for rotating said shaft to remove said projections from the path of the cam mechanism 55 to prevent operation of said shaft, the machine being thereby rendered capable of printing without calculating.

121. In combination a master gear wheel, 60 keys, positive gear connections between them so constructed that when the master wheel is held the keys cannot be depressed; a totalizer adapted to be operated in its different ordinal places successively by said master wheel, said totalizer having pointing-off 65 points therein formed by spacing the total-

izer parts into groups; and a locking member rigidly fastened in the totalizer at the pointing-off points therein for preventing the rotation of the master wheel at those points.

122. In combination a master gear wheel, 70 keys, positive gear connections between them so constructed that when the master wheel is held the keys cannot be depressed; a totalizer adapted to be operated in its different ordinal places successively by said master 75 wheel, said totalizer having pointing-off points therein formed by spacing the totalizer parts into groups; and a plate rigid in the totalizer said plate having projections thereon at the pointing-off points for engagement 80 with the master gear wheel and thus preventing the rotation of said master gear wheel at those points.

123. In a calculating machine, the combination with totalizer mechanism comprising 85 totalizing gears suitably arranged in groups, of driving mechanism connected with the keys of the machine, a driving gear associated with the driving mechanism, the totalizer mechanism and driving gear being relatively movable whereby said driving wheel may engage successively with the totalizer 90 gears of the groups, and means for preventing actuation of keys when said driving gear is in position between groups of the totalizer 95 gears.

124. In a calculating machine, the combination with totalizer mechanism comprising totalizer gears suitably arranged in groups, 100 of driving mechanism and printing mechanism associated with keys of the machine to be operated upon actuation thereof, a driving gear associated with the driving mechanism, the totalizer mechanism and driving gear being relatively movable whereby said 105 driving gear may engage successively with the totalizer gears of the groups, and means for preventing any operation of the printing and indicating mechanism when the driving gear is in position between groups of the 110 totalizing gears.

125. A calculating machine having a totalizer including tens carrying mechanism and non operative members located at certain of the ordinal places therein for preventing 115 the operation of the totalizer at such ordinal places.

126. A calculating machine having differential mechanism, the parts whereof are in positive gear connection so that if one part is 120 held the others are in consequence also held; and a totalizer adapted to be positively gear-connected to said differential mechanism to be operated thereby, said totalizer having fixed members at the pointing-off points for 125 holding the differential mechanism from action at such pointing-off points.

127. In a calculating machine the combination of a totalizer including figure wheels arranged in groups with spaces at the point- 130

ing-off points, positive geared key-connections for operating said totalizer, said key connections and totalizer being relatively movable for determining the ordinal value of
5 the key struck and means for preventing the depression of the keys when the totalizer and key connections are in the relative position corresponding with the pointing-off points of the totalizer.
10 128. A key operated machine including a totalizer having number wheels arranged in

groups with spaces between the groups for pointing off, and means located in correspondence with said pointing-off spaces for preventing the operation of the keys at such 15 pointing-off spaces.

In witness whereof, I hereunto subscribe my name this 28th day of March A. D., 1905.

JOHN C. WAHL.
